UNITED STATES PATENT OFFICE.

ISAAC S. DEMENT, OF EAST ORANGE, NEW JERSEY, ASSIGNOR TO AMERICAN MECHANICAL CASHIER COMPANY, OF NEW YORK, N. Y., A CORPORATION OF NEW JERSEY.

COMPUTING-MACHINE.

1,107,269.

Specification of Letters Patent. Patented Aug. 18, 1914.

Application filed May 1, 1903, Serial No. 155,150. Renewed September 5, 1912, Serial No. 718,712.

To all whom it may concern:

Be it known that I, ISAAC S. DEMENT, a citizen of the United States, and a resident of East Orange, in the county of Essex and 5 State of New Jersey, have invented certain new and useful Improvements in Computing-Machines, of which the following is a specification.

This invention relates to computing and 10 indicating machines and while the present improvements are especially valuable as applied to machines for computing, indicating, or otherwise facilitating money transactions, the invention as to some of its principles 15 may be employed in machines for mechanically computing, or indicating, other operations as those involving weights, measures, divisions of time, etc. Some of the principles of the invention moreover may be employed 20 in machines for mechanically performing various characters of computing operations as, for instance, subtraction, multiplication, and division, and some of the principles may be employed in machines for performing 25 computations with abstract numbers, and in machines for performing the computations with denominative and compound numbers. The invention is more particularly addressed however to machines for 30 mechanically performing the operations of subtraction, the principles involved being applicable both to machines for subtracting abstract numbers and to machines for subtracting compound numbers having either 35 uniform or varying scales. The machines referred to are characterized by a set or sets of finger keys, on which numbers may be indicated, means for giving the result of the computation and for indicating the operation, and connections between the keys and the result giving and indicating means.

Prior to the present invention the constructions employed in and proposed for the character of machine referred to have either 45 embodied a separate key or indicating device for each number used in the computation, or where interchangeable connections or "permutation" devices have been proposed, their number and arrangement have been determined empirically for each particular 50 computing operation, the result being that the machines have been complicated and not uniform and reliable in operation.

An object of the present invention is to 55 provide a machine whereby the computing,

or indicating operations are uniformly and reliably performed mechanically, and to provide a machine which nevertheless is simple and durable in construction and simple, uniform, and reliable in operation; also to provide a machine involving principles such that the character of the computing, or indicating operations to be performed thereby may be predetermined without empirical adjustment or arrangement of the parts and 60 without unnecessary complication. These and other objects of the invention will more fully appear from the following description.

This invention consists in the novel devices, combinations of devices, and improvements herein shown and described.

The accompanying drawings, which are referred to herein and form a part hereof, illustrate, as one embodiment of the invention, a machine for mechanically performing the operations of subtracting, and particularly for computing and indicating or registering the difference between an amount of money tendered in payment of a purchase and the amount of the purchase. An embodiment of the invention is also illustrated in which the result of the computation or other operation is given by the automatic delivery of an amount of money representing the difference between the amount of 85 money tendered and the amount of the purchase.

Of the drawings Figure 1 is a perspective view of a machine constructed in accordance with this invention; Fig. 2 is a vertical, central, longitudinal section of the same; Fig. 2^a is a section on line A—B, Fig. 4, illustrating a detail; Fig. 3 is a plan view of the machine with the top section of the inclosing case removed; Fig. 4 is a sectional plan view 90 of the machine taken on the line C—D of Fig. 2; Fig. 5 is a similar view taken on the line E—F of Fig. 2; Fig. 6 is a rear elevation of the machine with the rear section of the casing removed; Fig. 7 is a vertical section 100 illustrating on a larger scale that part of the machine located at the right in Fig. 2, the section being taken on the line G—H of Fig. 3; Fig. 8 is a similar view, the section being taken on the line I—J of Fig. 3; Fig. 105 9 is a sectional plan illustrating on an enlarged scale certain details, the section being taken on the line K—L of Fig. 7; Figs. 10 and 11 are sectional elevations taken on lines M—N and O—P, respectively, of Fig. 110

- 7 illustrating on an enlarged scale certain details; Fig. 12 is a vertical sectional view on the line Q—R of Fig. 7 looking in the direction of the arrows; Fig. 13 is a longitudinal section on the line S—T of Fig. 14 illustrating certain details; Figs. 14 and 15 are vertical sections on lines U—V and W—X, respectively, of Fig. 13; Fig. 16 is a vertical, central section on the scale of Fig. 7 illustrating another embodiment of the invention; Fig. 17 is a front elevation of the machine shown in Fig. 16 with the front section of the case removed, and certain parts shown in section to illustrate more clearly the construction; Fig. 18 is a transverse section of the same similar to Fig. 16 but looking in the opposite direction; Fig. 19 is a plan view of the same with the case removed and certain parts shown in section to illustrate more clearly the construction; Figs. 20 to 35 inclusive are diagrammatic views illustrating the principles of the construction and operation of the connecting means of the machine shown in Figs. 1 to 19, inclusive; Figs. 36 to 43 inclusive are similar views illustrating diagrammatically certain modifications of the connecting means; and Fig. 44 shows two cross sectional views of a detail.
- 30 A machine constructed in accordance with this invention comprises in general, means on which numbers may be indicated, the same being for the sake of brevity herein termed the "number indicating means", means for giving the result of the computation or other operation, the same being hereinafter termed the "result giving means", and connecting means between the number indicating means and the result giving means.
- 35 The number indicating means may consist of keys or similar devices representing figures or the elements of numbers. Where more than one number is employed in the computation or other operation, the number indicating means may include a corresponding number of members. Where finger keys are employed, the members of the number indicating means may consist of keys or
- 40 sets of keys on which the respective numbers may be indicated by depressing or otherwise manipulating the keys, each member having a separate section, as a key or group of keys, corresponding to each element of the number to be indicated thereon. A member of the number indicating means on which abstract numbers are to be indicated comprises sections representing the orders of the numbers, as units, tens, hundreds, etc.,
- 45 each section having elements corresponding to the various value-grades or steps in its order. A member on which compound numbers are to be indicated consists of sections representing the denominations of the number as the cents, dimes, and dollars denominations of United States money, or the days, months, and years denominations of numbers representing time, each section having elements corresponding to the units or steps of its denomination. Where computations or other operations involve one or more compound numbers including value elements made up of combinations or multiples of the units of one or more of the denominations, as, for instance, the "nickels", "quarters", fifty-cent pieces, two, five, twenty, and fifty-dollar bills of United States money, the result of the operation of the machine may depend upon which of such value elements is or are used. These value elements are herein termed "sub-denominations", the value of each being less than the full value of its denomination. When the result of any of the operations of the machine is dependent upon which of the sub-denominations is or are used, then the member of the number indicating means on which such a compound number is indicated includes at least one element corresponding to each of the sub-denominations, said member including also sufficient elements corresponding to the units of the various denominations to enable any amount to be represented.
- 50 The result giving means of the machine comprises sections corresponding to the orders or denominations of the numbers in which the result is to be expressed, said sections including elements corresponding to the steps or numerical elements of said numbers. Where, for example, the result is to be expressed in the denominational units and sub-denominations of a compound number, the result giving means includes elements corresponding to the units and sub-denominations in which the result is to be expressed. If the result is to be expressed in the orders of an abstract number, the result giving means includes a section corresponding to each order, each of which sections may consist of separate elements corresponding to each value-grade or step in the order. The denominations of compound numbers and the orders of abstract numbers are herein generically termed the "numerical places" of the numbers and the corresponding sections of the machine are termed the "numerical places" of the machine.
- 55 The connecting means between the number indicating means and the result giving means are such that the operations of the latter are controlled by the former. Obviously any suitable character of connections may be used. They may, for instance, be mechanical, electrical, or fluid. The connecting means may be actuated directly by the indicating means or the connecting means may be actuated by a means independent of the indicating means, in which

- case the indicating means serve merely to control the operation of the connecting means either by preventing their actuation or by rendering their actuation ineffective.
- 6 The connecting means moreover consists of members corresponding to the different numerical places of the machine, and where the result is dependent upon the sub-denominations of compound numbers, the connecting means includes also members corresponding to certain of said sub-denominations. Where the result to be presented by the result giving means is dependent upon more than one number indicated upon the number indicating means, the connecting means is generally controlled by both the members of the number indicating means upon which such numbers are indicated. Where, for example, the result depends upon the sub-denominations of a compound number indicated upon a member of the number indicating means, and also upon the steps of the orders of an abstract number indicated upon another member of the number indicating means, then the connections between the number indicating means and the result giving means are controlled by the elements of the number indicating means upon which the elements of the respective numbers are indicated.
- 30 A machine may serve to make a computation or it may serve merely to indicate a transaction; for instance, it may serve to indicate an amount of money paid in or an amount of money paid out, or it may serve to indicate one or more of the numbers involved in a computation as well as the result of the computation. The result of the operation of the machine may be given either as a mere visible indication, or the result may be permanently indicated, or the result may be given by actually performing the operation automatically. That is to say, the result giving means may present the result of an operation by means of suitable signs which are brought into view, or the result giving means may consist of printing devices for permanently indicating the partial or complete operations of the machine, or said means may serve to receive amounts of money paid in or to mechanically deliver amounts of money paid out as change or otherwise, or to both receive and deliver said amounts.
- 65 The particular embodiment of the invention illustrated in the drawings consists in the main of a machine for subtracting one compound number from another, when the differences between the two numbers is less than the lowest sub-denomination or denominational unit of the greater number or subtraction, the particular object in view being to compute the change between an amount of money presented for the payment of a purchase and the purchase price. The machine

shown also includes in its organization means whereby an amount of money paid out by the user of a machine may be presented by the result giving means. The machine also includes means for indicating the amounts of the purchase prices indicated on the number indicating means.

In the embodiment of the invention illustrated in Figs. 1 to 15, inclusive, the result giving means comprises indicators constructed to present to view numbers or signs representing the pieces of money employed to complete a transaction indicated on the machine, a cash drawer being automatically opened at the same time to enable the operator to select pieces of money to be paid out either as change or otherwise.

Referring now in detail to the machine illustrated in Figs. 1 to 15, inclusive, 1 represents a casing in which the various parts of the machine are mounted. The number indicating means of this machine comprises two members, one consisting of a set of finger keys on which amounts of money received are indicated, and the other, of a set of finger keys on which numbers representing purchase prices and amounts to be paid out are indicated. The first set of keys, herein termed the "deposit keys," is arranged in a single row 2 across the front of the machine. By reason of the fact that the result is more or less affected by the particular money elements of which an amount received is made up, there is provided at least one deposit key corresponding to each money element which the machine is designed to manipulate. The deposit keys consist of sections, one section for each numerical place of the machine, said sections being preferably arranged in accordance with the successive numerical places and the keys representing the sub-denominations of each place being arranged in the order of the values represented by them. The second set of keys, herein termed the "purchase keys," is arranged in groups or sections corresponding to the orders or denominations of the numbers representing the purchase prices to be indicated on the machine. As the sub-denominations of a purchase price do not in any way affect the result, the sub-denominations do not need to be represented by the elements of the purchase keys. Where the denominations of a monetary system which a machine is designed to manipulate, correspond, so far as they go, to the decimal places of abstract numbers, as is the case with the United States, French, and German systems, for instance, the purchase keys are arranged in sections representing the orders of such numbers. As the machine shown is designed to manipulate nothing of less value than the five-cent piece, the units or cents section consists of a single purchase key 3. The tens, hundreds, and thousands

sections, consist each of a row of nine keys representing the nine value-grades or steps in the respective orders, said rows being referred to by numerals 4, 5, and 6 respectively.

It is obvious that other types of number-indicating devices than the rows of separate keys referred to as constituting each section of each member of the number-indicating means may be used, if desired.

The result giving means in the machine shown consists of a series of wheels or cylinders 7 on the circumferences of which are placed numbers corresponding to the sub-denominations of the monetary system which the machine is designed to manipulate. These cylinders 7, which correspond in number and arrangement to the deposit keys, are loosely journaled on a shaft 8 fixed in the frame of the machine at a point slightly above and to the rear of the keys 2. The front wall of the casing 1 is provided with an opening 9 adapted to expose a portion of the surface of the cylinders 7 to the view of the operator. It is obvious that other forms of indicating devices may be used in place of the cylinders 7.

The connecting means between the members of the number indicating means and the result giving means, in accordance with the construction shown, consists in the main of a system of independently movable mechanical connections, the members of said connecting means comprising various sets 35 of connections corresponding to the various numerical places of the machine. The members of said connecting means include also various auxiliary sets corresponding to certain sub-denominations. The sets of connections corresponding to the respective numerical places of the machine may be composed of separate and independent elements, or each set may be composed in whole or in part of the same members which form 45 another set or sets. Some of the auxiliary sets are composed of independent elements and some of them are composed in whole or in part of elements forming parts of other sets. The sets of connections corresponding 50 to the various numerical places of the machine are controlled in any suitable way by the purchase keys. In the particular embodiment of the invention illustrated, the elements of the connecting means consist of 55 independently movable sliding bars. Referring to Figs. 3 and 4, 3^a represents the set of bars corresponding to the lowest numerical place of the machine, said set being herein termed the "units set." 4^a represents the set of bars corresponding to the second numerical place and termed the "tens set"; 5^a represents the set corresponding to the third numerical place and termed the "hundreds set." 6^a is the single bar corresponding 65 to the fourth numerical place, said bar

representing what is termed the "thousands set." The units set 3^a of bars or connections is rendered operative, in a manner explained below, by the key 3 forming the units section of the purchase keys. This set 70 of bars extends throughout all the numerical places in the machine and when it is operative all other of the main set are inoperative. The tens set 4^a is rendered operative by any one of the keys forming the tens section or row 4 of the purchase keys, provided section 3 is not operated. The set 4^a extends through the second numerical place of the machine and all numerical places above the second. The hundreds set 80 5^a is rendered operative by any one of the keys forming the hundreds row 5 of the purchase keys, provided either of the sections 3 or 4 is not operated. The hundreds set 5^a extends throughout the third and 85 fourth numerical places of the machine. The thousands bar 6^a is rendered operative by any one of the keys forming the thousands row 6 of the purchase keys. The bar 6^a is located only in the thousands set. Of course if the machine included more steps in the fourth numerical place or more than four numerical places, the various sets of connections would extend through the higher steps and places in the manner indicated. 90 The tens set 4^a in all numerical places above the second is composed of the same elements as those composing the units set 3^a above the second place. The hundreds set 5^a above the third numerical place is composed of 100 the same bars that form the connections for the sets 3^a and 4^a in the fourth numerical place.

The connecting bars may be mounted to move independently in any suitable way. 105 As shown in Figs. 2 and 4, the bars are mounted side by side to slide in the direction of their length in a series of three transverse supporting girders 11, 12, and 13. While the entire system of bars or the operative set thereof may be moved during each operation of the machine, certain of them being rendered inoperative by changing their positions or the positions of the parts moved by them, the bars in the embodiment of the invention illustrated are normally locked, the set controlling keys serving to unlock and thereby render operative the corresponding sets of bars. Such elements of the operative set of bars as are 110 not rendered inoperative by the actuation of the keys are moved by means independent of the keys. As shown, a series of arms 14, one for each bar, is loosely pivoted on a transverse shaft 15 fixed in the casing adjacent to the forward ends of the bars. Each arm 14 is provided with a pin 15^a adapted to engage the end of the corresponding bar and is connected at its lower end to a tension spring 16 which acts when the corre- 130

sponding bar is released to move the bar rearward a limited distance. The bars are normally held in their retracted positions by any suitable means adapted to release them when it is desired to transmit the effect of the indicating means to the result giving means. As shown, each of the bars is provided near its rearward end with a depending lug or projection 17 adapted to be engaged by a transverse bar 18 which is mounted at its opposite ends on a pair of arms 19 pivoted near the bottom of the casing. The arms 19 are provided with friction rollers adapted to engage a pair of cams 20 fixed to a shaft 21 journaled near the lower part of the casing and driven through one revolution during each operation of the machine. When the shaft 21 is stationary, the high parts of the cams 20 are in position to hold the connecting bars in their forward or inoperative positions. When the shaft 21 is rotated, the bar 18 will first permit the operative connecting bars to move rearward, and after they have performed their function, it will return them to their normal inoperative positions. The shaft 21 may be driven by any suitable means, hand or power operated. As shown, it is driven from the main power shaft 23 by a sprocket chain 22. The shaft 23 is provided with a hand crank 24 by means of which the shaft is rotated through one revolution to complete the operation of the machine after the number indicating means has been actuated.

The connecting bars may be normally locked by any suitable locking means adapted to be rendered ineffective by the actuation of the number indicating means. As shown, the locking devices for the bars consist of a series of transverse rockers pivotally mounted adjacent to the sliding bars and adapted to engage suitable locking projections on the bars. The rockers which control or render operative the various sets of bars are for convenience located beneath the bars, as shown in Figs. 2, 2^a, and as indicated in the plan view Fig. 4. Where the sets of bars are made up in part of the same elements, as in the machine shown, the set controlling locking devices are constructed of independently movable sections so connected that when the bars forming one set are unlocked, the bars not included in that set are locked. As the elements of the set 3^a of connections above the second numerical place of the machine also constitute a part of the set 4^a, and as the elements of the set 3^a above the third place also constitute a part of the set 5^a, the locking devices for the set 3^a consist of three independently movable sections, one corresponding to the two lower numerical places of the machine, and one for each of the two higher places. The section corresponding to the two lower places consists of a plate 25 loosely pivoted along one edge on a rock shaft 26 which is journaled near its opposite ends in auxiliary frame pieces 27, 28, and 29. The free edge of this section 25 is normally held up in the paths of alternating projections formed on the lower edges of the set 3^a corresponding to the two lower numerical places of the machine, a tension spring 30 (see Fig. 2^a) being provided for this purpose. The second section of these locking devices consists of a plate 31 fixed on the shaft 26. The free edge of the plate 31 is adapted, when in operative position, to engage downwardly projecting lugs on each of the set 3^a of bars corresponding to the third numerical place of the machine. The third section of this locking device corresponding to the fourth numerical place, consists of a plate 32 similar to the plate 25 and similarly mounted on the shaft 26. The plates 31 and 32 are normally retained in their locking positions by means of tension springs 33 and 34 similar to the spring 30, said springs 33 and 34 being indicated in the plan view Fig. 4. The plate 25 is operated by the units section of the purchase keys. As there is but one units key in the machine shown, to-wit, the five-cent key 3, the plate 25 is directly connected to the stem of that key, as shown in Fig. 4. Any suitable means may be provided to operate the sections 31 and 32 of this locking means to release the bars of the set 3^a whenever the section 25 is operated and at the same time permit the sections 31 and 32 to be operated independently of the section 25 and independently of each other, as required to render the sets 4^a and 5^a independently operative. In accordance with the construction shown, the section 25 is provided at one end with a lateral projection 35, which is adapted to overlie an arm 36 on the shaft 26 to which the section 31 is affixed, and the section 31 is provided at one end with a projection 37 adapted to overlie one end of the section 32. As the bars forming that portion of the set 4^a corresponding to the second numerical place of the machine are independent of the bars forming the set 3^a, the locking device for the set 4^a includes in addition to the sections 31 and 32 of the locking device for the set 3^a the third section which is operated independently of the locking device 25 for the set 3^a. As shown, this third section consists of a plate 38 which is fixed on the shaft 39 journaled in the frame sections 28 and 29. This plate is normally held in locking position by the tension spring 40. Any suitable means may be provided for operating the plates 31, 32, and 38 from any one of the keys 4 corresponding to the second numerical place of the machine. The means shown consists of a sliding bar 41 so connected to each of the keys 140

4 as to be moved by the actuation of any one of said keys. As indicated in Fig. 2^a, the bar 41 is mounted to slide in grooves of the girders 11 and 12 and is provided with 5 depending arms 42 and 43 arranged to come in contact with the forward surfaces of an arm 44 of the shaft 26 and an arm 45 of the shaft 39 respectively. The bar 41 is normally held in its forward or retracted position 10 by means of a tension spring 46 which is connected at one end of the bar and at the other end of the girder 11. By reason of this construction the shafts 26 and 39 and the locking plates controlled thereby will 15 be operated by each forward movement of the bar 41 and at the same time said shafts and plates may be operated independently of the bar 41. As the bars forming that portion of the set 5^a corresponding to the 20 third numerical place of the machine are independent of the bars forming the sets 3^a and 4^a, the locking device for the set 5^a includes in addition to the section 32 of the locking devices for the sets 3^a and 4^a a section 25 which may be operated independently of the sections 25, 31, and 38. In accordance with the construction shown, this independent section consists of a plate 48, which is fixed on the shaft 49 journaled in the auxiliary frame sections 27 and 28 in line with the shaft 39. The plate 48 is normally held in its locking position by a tension spring 50 similar to the spring 40, see Fig. 4. The plates 32 and 48 may be operated from any 30 one of the keys 5 corresponding to the third numerical place of the machine by any suitable means. In accordance with the construction shown, this means consists of a sliding bar 51 similar to the bar 41 and similarly mounted and connected to operate the arms 54 and 55 of the plates 32 and 48 respectively. As there is only one bar corresponding to the fourth numerical place of the machine, the locking device for that bar 40 consists of but one section which is operated independently of any of the other locking sections by the actuation of any one of the keys 6 corresponding to the fourth numerical place of the machine. This locking device 45 consists of a plate 58 which is loosely journaled on the shaft 49 (see Fig. 4). This plate is normally held in operative position by a tension spring 60 similar to the springs 40 and 50 and it is operated to unlock the bar 6^a by a sliding bar 61, operatively connected with an arm 62 of the plate 58, this construction being similar to that of the bar 41, and its connection with the arm 45 of the plate 38.

50 Where a machine is designed to subtract one number from another and give correct results only where the difference between the two numbers is less than the value of the lowest numerical element of the greater number, as in a machine for computing

change, or the difference between an amount of money tendered and the amount of the purchase price, which difference is always less than the value of that one of the pieces of money making up the amount tendered which has the lowest denomination, like the machine shown, it is necessary that all sets of connections except that corresponding to the lowest numerical place represented by the actuated keys of the number indicating means must be rendered inoperative whether or not any key or keys of a higher numerical place have been actuated. This may be accomplished by any suitable means. In accordance with the construction shown, a locking device is provided having sections corresponding to the independent sections 25, 31, and 32 of the locking device for the set 3^a of connections. As shown, this auxiliary locking device consists of a plate 65 similar to the plate 25 and similarly mounted along one edge on a shaft 66 journaled in the frame sections 27, 28, and 29 in a parallel relation to the shaft 26. The section of the locking device corresponding to the third numerical place of the machine consists of a plate 67 similar to the plate 31, said plate 67 being fixed on the shaft 66. The section of this locking device corresponding to the fourth numerical place of the machine consists of a plate 68 corresponding to the plate 32, said plate 68 being loosely mounted on the shaft 66. The locking sections 65, 67, and 68 are so connected to the corresponding locking sections 25, 31, and 32 that whenever any one of the latter sections is moved out of its locking position, the corresponding section 65, 67, or 68 is moved into locking position and vice versa. In accordance with the construction shown, the connections are as follows (see Fig. 4): The sections 25 and 65 are each connected to one of a pair of gear wheels 70, 71 which are loosely journaled on the shafts 26 and 66. The sections 31 and 67 are caused to move in unison by means of a pair of gear wheels 72 and 73 which are fixed to one end of the shafts 26 and 66. The sections 32 and 68 are caused to move in unison by means of a pair of gear wheels 74 and 75 loosely mounted on the shafts 26 and 66. When in locking position the free edge of the section 65 lies in the paths of locking projections suitably formed on the under surfaces of those bars of the set 4^a which correspond to the second numerical place of the machine. In a similar manner the plate 67 is adapted to lock those bars of the set 5^a corresponding to the third numerical place of the machine. The plate 68 is adapted to lock the bar 6^a corresponding to the fourth numerical place of the machine.

In order that the machine may correctly perform any subtraction or other operation within its capacity means are provided

whereby certain of the operative set of connections may be rendered inoperative in each or any of the numerical places throughout which the operative set extends, the connections which are rendered inoperative in any numerical place being dependent upon which of the keys of the number indicating means corresponding to that numerical place had been actuated. To this end each of the keys 13 or elements of each member of the number indicating means is provided with means whereby one or more of the operative set of connections may be rendered inoperative. In the embodiment of the invention illustrated these means consist of auxiliary locking devices, which upon the depression of the key prevent the bars controlled thereby from effecting their operative movement. As shown, the auxiliary locking devices 15 corresponding to the purchase keys consist of a series of oscillating rockers similar to the set controlling locking devices above described, said auxiliary rockers being located above the bars, as shown in Figs. 2 and 3. As the 20 units section of the purchase keys in the machine shown consists of a single key 3, no auxiliary locking device is required for that key. The auxiliary locking devices for the keys 4 corresponding to the second numerical place of the machine consist (see 25 Figs. 2, 2^a, and 3) of a series of plates 80, one for each of the keys 4, said plates 80 being fixed on transverse shafts 81 journaled in the frame sections 28 and 29 and connected to the stems of the respective keys by 30 arms 82. The keys are normally retained at the upper limits of their movement with the plates 80 in their inoperative positions by means of the light compression springs 4^a 35 confined between the top plate of the casting 1 and the heads of the keys as shown in Figs. 2 and 2^a. The locking plates for the keys 5 corresponding to the third numerical place of the machine consists of a series of 40 plates 84, one for each of said keys, said plates 84 being loosely mounted on shafts 85 journaled in the frame sections 27 and 28 in line with the shafts 81. The plates 84 are directly connected to the corresponding 45 keys by means of suitable projections on the ends of the plates which enter perforations in the stems of the keys as indicated in Fig. 3. The keys 5 together with the plates 84 are normally retained in their inoperative 50 positions in the same manner as the keys 4 and plates 80. The auxiliary locking devices for the keys 6 corresponding to the fourth numerical place of the machine consists of a series of plates 86 fixed on the 55 shafts 85 and connected to the corresponding keys by means of arms 87 which, as shown, (see Fig. 3) project through suitable slots in the plates 84 and enter openings in the stems of the keys 6. The keys 6 and 60 locking plates 86 are normally retained in

operative position in the manner described in connection with keys 84 and plates 80.

While any suitable means may be provided for actuating the universal bars 41, 51, and 61 from the respective sets of keys 4, 5, and 6, said bars may be conveniently operated in the manner illustrated in Fig. 2^a. As here shown, the bar 41 is provided with an upwardly extending projection corresponding to each one of the keys 4 and each one of the plates 80 is provided with a downwardly extending projection 88 adapted to engage the forward surface of the corresponding projection. By reason of this construction it will be seen that whenever any one of the keys 4 is depressed, the bar 41 will be moved backward as required to operate the locking devices connected therewith. The bar 51 is operated in a similar manner from the locking plates 84 corresponding to the keys 5 and the bar 61 is operated from the plates 86 corresponding to the keys 6.

Whenever any purchase key has been actuated together with its locking device it must be retained in its actuated position until the shaft 23 has been rotated to complete the operation of the machine. Any suitable means may be provided for retaining the purchase keys in their actuated positions. As shown, each of the keys in each key section is pivotally connected at its lower end to a pivoted yoke 89^a. Each of the yokes 89^a is provided with an upwardly extending lug which passes through a suitable opening in a sliding bar 89, one of the bars 89 being provided for each row of purchase keys, as clearly shown in Fig. 5. The bars 89 are normally held in a rearward position by means of tension springs 89^b suitably connected to an upwardly projecting arm near the forward ends of the bars, and an extension of the horizontal frame plate 89^c. Whenever a key is depressed the corresponding locking bar 89 will be retracted by the finger on the corresponding yoke 89^a until that finger slips out of the opening in the bar. The bar will then snap back to its original position so as to lock the yoke 89^a together with its key in its depressed position. For the purpose of releasing the deposit keys after the shaft 23 has been actuated to complete the operation of the machine, any suitable means may be provided. The means provided for this purpose in the machine shown will be hereinafter described.

Where a machine is designed for computing change, as is the case with the machine shown, the devices corresponding to the deposit keys for rendering inoperative certain parts of the operative set of connections are so constructed as to render inoperative the connections corresponding to the elements or sub-denominations represented by the ac-

tuated deposit keys and all connections corresponding to all numeral places and to all elements and sub-denominations of a higher value than the lowest value represented by 5 the actuated deposit keys. In the machine illustrated the devices actuated by the deposit keys for rendering certain of the operative set of connecting bars inoperative consist of a series of independently movable 10 members, one for each of the deposit keys, arranged to engage with suitable locking projections on the bars so as to prevent operative movement of said bars. As shown, these auxiliary locking devices consist of a 15 number of yokes 90 loosely pivoted on a transverse shaft 91 above the systems of connections and adjacent to the pivots of the keys 2, as shown in Figs. 2, 4, and 7, said shaft 91 being journaled at its opposite ends 20 in the auxiliary frame pieces 92 and 93. The yokes 90 are normally held in their inoperative positions by the detent springs 94 carried by a rod 95 fixed in the frame pieces 92 and 93 adjacent to the rod 91. For the 25 purpose of throwing the yokes 90 down into their operative positions by the actuation of the corresponding deposit keys, each of the yokes is provided with a projection 96 which normally lies in the path of a finger 30 97 forming an extension of the corresponding deposit key. In order to render inoperative all elements of the operative set of connections which correspond to a higher value than the lowest value represented by 35 35 the actuated deposit keys, each of the yokes 90 is provided with a lateral projection 98 which overlies the adjacent yoke corresponding to a higher value so that whenever any yoke is actuated, all yokes corresponding 40 to the higher values are also actuated or rendered operative to lock the connecting bars. For the purpose of returning the yokes 90 to their normal positions upon the completion of an operation of the machine, 45 45 the shaft 91 is provided with a spline 99, said spline being arranged to engage a suitable recess in each of the yokes 90 so that when the shaft is turned backward, the yokes will be carried back with it to their 50 normal inoperative positions. To permit any one or more of the yokes to be operated without operating the yokes corresponding to lower values, each of the yokes has a limited movement independent of the shaft, the 55 recesses being suitably extended for this purpose. The shaft 91 is operated to return the yokes by means of an arm 100 which is actuated by a suitable part of the mechanism as hereinafter described.

60 In the embodiment of the invention illustrated the members of the connecting means include various auxiliary sets of connections corresponding to certain of the sub-denominations represented by the deposit keys.

65 These auxiliary sets are wholly or in part

normally inoperative and are rendered operative by the actuation of the deposit keys to which they correspond. In the particular machine shown, an auxiliary connecting bar or set of bars is provided for the first step 70 or dimes of the second numerical place and also for the second step or twenty-five cent piece of the second place, also for the second step or two-dollar sub-denomination of the third place, and also for the third step or 75 five-dollar sub-denomination of the third place. These auxiliary sets of bars are termed respectively the "10 set", the "25 set", the "2 set", and the "5 set". The auxiliary sets of connections are composed, 80 for reasons hereinafter more fully explained, of members corresponding to and rendered operative with the members of the various main sets of connections, and the auxiliary sets may in fact be composed in part of the 85 bars forming parts of the main sets. Such of the auxiliary sets as are not formed of bars which also constitute parts of the main sets of connections, are controlled or rendered operative by the corresponding deposit 90 key or keys. In the machine shown, the 10 set, (see Figs. 3 and 4) consists of a single bar marked 3¹⁰, said bar being rendered operative by either one of the two deposit 95 keys corresponding to the dimes. The bar, however, although unlocked by the actuation of the dimes key, is not permitted to operate except when the units key 3 has been actuated. The bar 3¹⁰ will be seen, therefore, to form in effect a part of the units set 3 of 100 connections. The 25 set of auxiliary connections comprises those connections necessary to compute the change required when the twenty-five cent deposit key has been actuated. This auxiliary set includes connections which are rendered operative with the units set 3^a, and other connections which are rendered operative with the tens set 4^a. Those bars which are rendered operative with the units set 3^a, are marked 3²⁵, and those bars which are rendered operative with the tens sets 4^a, are marked 4²⁵. As 105 will be seen by a reference to Figs. 3 and 4, this auxiliary set of connections is mainly composed of bars which form parts of the units and tens sets of connections, only one of the bars 4²⁵ being controlled by the twenty-five-cent deposit key. The 2 set of auxiliary connections consists of one bar marked 3² and 4², said bar being rendered operative with both the units set 3^a and the tens set 4^a of connections, and another bar marked 5² which is rendered operative with the hundreds set 5^a of connections. These 110 bars are controlled by the two-dollar deposit key. The 5 set of auxiliary connections consists of a bar marked 3⁵ and 4⁵, said bar being rendered operative both with the units set 3^a and with the tens set 4^a of connections, and another bar marked 115 120 125 130

5^s which is rendered operative with the hundreds set 5^a of connections. This auxiliary set is controlled by both the two-dollar and the five-dollar deposit keys, and 5 is only rendered operative when both sets of keys are actuated. When an auxiliary set of connections is rendered operative, some or all of the elements of the operative main set of connections corresponding to 10 the sub-denominations represented by the auxiliary set and all elements of the operative main set corresponding to higher values are rendered inoperative. An auxiliary set usually extends through all steps 15 in the numerical place of the controlling sub-denomination which represent a lower value than said sub-denomination and in some instances the auxiliary set extends to the lower numerical place. In some instances an auxiliary set is rendered operative whenever the deposit key of the corresponding sub-denomination is actuated, whether that key is actuated more than once during the same operation or not; 20 whereas, in other instances the auxiliary set is only rendered operative when the key of the corresponding sub-denomination has been operated in a certain manner, as for instance, on the first and every alternate 25 operation of the key. The reasons for this will be hereinafter fully explained.

Any suitable means may be provided for controlling or rendering operative the auxiliary sets of connections. In accordance 30 with the embodiment of the invention illustrated the deposit key controlled auxiliary connections are normally locked against operative movement, the same being unlocked or rendered operative when the corresponding 35 deposit keys are actuated, the mechanism for controlling said connections serving also to lock certain elements of the operative main set of connections. In the machine shown, two of the auxiliary sets, together with the 10 set and the 2 set are rendered operative whenever the dime and two-dollar keys are actuated. The 25 set on the other hand is only rendered operative when the twenty-five cent key is actuated once or an 40 odd number of times. The 5 set is only rendered operative when the five-dollar key is actuated once or an odd number of times together with the two-dollar key.

The means for controlling the 10 set of 45 connections is illustrated in Figs. 4, 7, and 10. As shown, this mechanism consists of a sleeve 101 which is loosely mounted on a rod 102 fixed in the auxiliary frame pieces 92 and 93 above the system of connecting bars 50 and at a suitable point below the deposit keys 2. The sleeve is provided at one end with a yoke 103, the transverse bar of which is arranged to traverse the plane of the bar 3^a corresponding to the lowest numerical place 55 of the machine, and also the planes of the bars 3^a and 4^a corresponding to the lowest step of the second numerical place. The yoke 103 is connected at its end farthest from the sleeve 101 with a ring 104 which is connected to a second yoke 105. The yoke 105 is arranged in the planes of the two bars forming the auxiliary set 3¹⁹. The yokes 103 and 105 are arranged at such an angle with relation to each other that when one of them is in operative position with relation to suitable locking shoulders formed at a suitable point on the upper edges of the bars, the other yoke is out of locking relation with said shoulders. This locking device is normally held in a position to render the auxiliary set inoperative by means of a tension spring 106. For the purpose of shifting this device to its opposite position whenever one of the dimes keys is actuated a pair of push bars 107 and 108 is provided, said bars being slidably mounted on suitable fixed brackets 109 and 110 in line with and just below the dime deposit keys 2 and pivotally connected at their lower ends to suitable arms on the sleeve 101. For the purpose of retaining the sleeve 101 and the locking devices connected thereto in their actuated 80 positions against the tension of the spring 106 a detent arm 111 is provided, the same being loosely mounted by means of a sleeve 90 112 on a fixed rod 113 and arranged to engage at its free end a suitable shouldered rib on the sleeve 101 arranged below the system of connections, as shown in Fig. 7. The sleeve 112 is provided with a rearwardly extending arm 114 arranged in the path of a cam 114^a on the shaft 23 whereby the arm 111 is caused to release the sleeve 101 at the end of each operation of the machine.

The locking device for the auxiliary set 2² 105 is similar in construction to that just described. As shown in Figs. 2 and 10, this device consists of a sleeve 115 loosely journaled on the rod 102 and connected at one end to the yoke 116 which, as shown, is connected by suitable intermediate rings journaled on the rod 102 to yokes 117 and 118. The yokes 116 and 118 are arranged to traverse the planes of the bars forming those elements of the sets 3^a, 4^a, and 5^a corresponding to the two one-dollar steps of the third numerical place of the machine and the yoke 117 is arranged to traverse the planes of the bars forming the 2² set. The yokes 116 and 118 on the one hand and the yoke 117 on the other hand are arranged at such angles with relation to each other that when the yokes of one angle are in operative position the yoke of the other angle is out of operative position and vice versa. The sleeve 115 is operated from the two-dollar deposit key by means of a pusher 119 slidably mounted on a fixed bracket 120 and pivoted at its lower end to a suitable arm on sleeve 115. The sleeve 115 together with the yokes carried 115 120 125 130

thereby is normally held in position to render the auxiliary set 2² inoperative by means of a tension spring 121, see Fig. 2. For the purpose of retaining the sleeve 115 and the yokes carried thereby in their actuated position a detent arm 122 similar to the arm 111 is provided (see Fig. 5), said arm being mounted on a sleeve 123 which is journaled on a rod 113 and is provided with a rearwardly extending arm 124 arranged in the path of a cam 126 on shaft 23 whereby the detent is released as hereinafter explained. The detents 111 and 122 are yieldingly held in operative position by suitable springs one of which is shown at 125 in Fig. 2.

The locking devices by which the 25 and the 5 auxiliary sets are controlled are illustrated in Figs. 2, 7, and 11. Referring more particularly to Fig. 11, the locking device for the 25 set will be seen to consist of a sleeve 130 loosely journaled on a rod 131 fixed in the auxiliary frame pieces 92 and 93. Near one end the sleeve 130 is provided with two series of locking projections 132 and 133 which consist of three projections arranged at angles of 120 degrees, the projections of one series being staggered with relation to the projections of the other series as indicated in Figs. 2 and 4 and shown in Fig. 11. One of these two series of projections is arranged in the plane of the bar forming the auxiliary set 3¹⁰ and the other series is arranged in the plane of the right-hand bar 4²⁵ of the 25 set. One of the projections of the series 132 is normally in position to lock the bar 4²⁵, the bar 3¹⁰ being normally released. The sleeve 130 is provided at its opposite end with a ratchet wheel 134 having six teeth, the same being engaged by a pawl 135 pivotally mounted on an oscillating pawl arm 136 loosely mounted on the rod 131. For the purpose of turning the ratchet through the space of one tooth by each actuation of the twenty-five-cent deposit key a push bar 137 is provided the same being slidably mounted on a fixed bracket 138 and pivotally connected at its lower end to the oscillating arm 136. It will be seen that on each alternate actuation of the twenty-five-cent key the locking projections 132 and 133 will by reason of the staggered arrangement be returned to one of their normal positions. For the purpose of returning this locking device to one of its three normal positions after each single operation of the machine, if it is not left in one of its normal positions by the actuations of the twenty-five-cent deposit key, the sleeve 130 is provided at a suitable point with three pins 140 arranged at angles of 120 degrees. An oscillating finger 141 is arranged to strike the pins 140, said finger being for convenience loosely mounted on the fixed rod 95. The finger

141 is provided with an arm having a pivoted connection with an actuating arm 142 which is mounted on the sleeve 112. To prevent backward movement of this locking device a detent pawl 143 is provided, the same being pivoted on the rod 95 in position to engage the ratchet 134. For the sake of clearness the ratchet 134 is represented in Fig. 2 as being placed in front of or to the right of the locking sections 132 and 133. The pawl arm 136 together with the push bar 137 may be returned to their normal positions by any suitable means as by a tension spring 144, see Fig. 7.

The locking device by which the auxiliary 5 set of connections is controlled is the same in construction as the locking device for the 25 set just described except as to the proportions and relative location of the sets of projections thereof. This mechanism, therefore, need not be specifically described except to state that the sets of locking projections 145 and 146 are respectively arranged in the planes of the connecting bars forming the 2 and 5 sets. The set of locking projections 145 are normally held in position to lock the bars of the 5 set the bars forming the 2 set being normally unlocked.

Auxiliary set controlling locking devices 95 of the character of those by which the auxiliary sets 10 and 2 are controlled, are, for the sake of brevity, termed "oscillators," as they have an oscillating movement, at each limit of which one or more members of the 100 device are in operative position. Auxiliary set controlling locking devices of the character of those by which the auxiliary sets 25 and 5 are controlled are herein termed "alternators" as they operate upon alternate 105 actuations of the twenty-five-cent and five-dollar deposit keys to lock one set of bars and unlock another set.

The effect of the operation of the connecting bars may be communicated to the result giving means in any suitable way. In accordance with the construction shown, each of the cylinders 7 forming an element of the result giving means, is provided with a spring 150 which is secured at one end to 110 the cylinder and at the other end to the fixed shaft 8 in any suitable way, as by means of a bracket 151 fixed to the shaft 8 and between the hub of which and a collar 152 fixed on the shaft the cylinder 7 is confined. The spring 150 serves to hold the cylinder 115 in contact with a spring controlled pivot detent 153, the cylinder being provided with a suitable lug 154 or projection adapted to engage the detent. The detents for all of the cylinders are pivotally mounted on a transverse rod 155 and located for convenience below and to the left of the cylinder, as shown in Figs. 2 and 7. Each of the cylinders 7 is left blank on that portion of its face which 125 130

is opposite the opening 9 in the casing 1, when the lug 154 is in contact with the detent 153. Just above the blank portion of the cylinder the surface is provided with a figure or mark indicating the value of the step or sub-denomination to which the particular cylinder corresponds. This arrangement of the figures is shown in Fig. 12. To render the cylinder operative to present to view the number thereon it is only necessary to release the detent 153 and permit the spring 150 to rotate the cylinder a limited distance. In accordance with the construction shown the operative movements of the cylinders are limited to a transverse stop bar 156 which is located a suitable distance above the detents 153 and in a position to engage the lugs 154 of the cylinders, when the same have been released by the detents. The cylinders may be returned to their normal positions by any suitable means. Preferably, however, they are left in the positions to which they are set by one operation until the machine is used for the next operation. To this end the stop bar 156, in accordance with the construction shown, is so connected with the deposit keys 2 that the actuation of any one of the deposit keys will serve to return the cylinders to their inoperative positions. As shown in Figs. 3, 7, 8, and 9, the stop bar 156 is mounted on a pair of arms 157 which are loosely journaled on the shaft 8 on the opposite ends of the series of cylinders 7 so that the plate 156 may lie close to the surfaces of the cylinders 7 and move concentrically therewith. The arms 157 are connected by links 158 to the ends of a pair of levers 159 which are loosely journaled near the opposite ends of a fixed rod 160 on which the deposit keys 2 are pivoted, said levers 159 carrying at their opposite ends a transverse bar 161 which is located beneath the keys 2 so that the operation of any one of the keys will rock the levers 159. The movement thus imparted to the levers 159 will be transmitted to the bar 156, the direction of the motion being such as to return the cylinders 7 to their normal positions. For a purpose hereinafter described the link 158 in accordance with one embodiment of the invention is made extensible so as to permit a limited movement of the levers 159 independently of the bar 156. As shown, the links 158 are formed of closed coil tension springs, the springs being so wound as to have a sufficient initial tension to return the cylinders 7 to their normal position. With this form of construction the movement of the arms 157 is limited in each direction by means of fixed stops 162 and 163, see Fig. 8. The movement of the connecting bars may be rendered effective for releasing the detents 153 directly or indirectly by any suitable means. As shown, the movement of the bars is transmitted to the detents indirectly by the following mechanism. A sliding frame consisting of the vertical bars 165 and transverse bars 166, 167, and 168 is arranged transversely of the machine in a plane adjacent to the rear ends of the system of connecting bars, said frame being mounted on the plates 92 and 93 by means of the pins 169 and 170 which engage slots in the bars 165 so as to permit a limited vertical movement of the frame. Loosely pivoted on the transverse bar 167 of this frame is a series of dogs 171, one dog being provided for each of the detents 153. The dogs 171 have, as shown in Fig. 4, wide contact surfaces which lie adjacent to the rear ends of the system of connecting bars, the face of each dog being adapted to be engaged by any one of the connecting bars corresponding to the element of the result giving means which is controlled by that dog. Each of the dogs 171 is provided with a pin 172 which normally lies in front of the depending contact portion 173 of the corresponding detent 153. Whenever a dog 171 is moved to the rear by the actuation of any one of the corresponding connecting bars the pin 172 will be brought beneath the contact portion 173 of the detent, so that when the frame 165 is raised, the detent will be actuated to release the corresponding cylinder 7. In accordance with the construction shown the frame 165 is raised during each operation of the machine by a pair of cams 174 on the shaft 21.

In addition to indicating the result of a computation or other operation on the machine, it is desirable, in a machine for computing change, to have means for indicating the amount of money presented for the payment of a purchase. While such an indicator might be separated from and independent of the result giving means, it is in the embodiment of the invention illustrated made a part of the result giving means. As shown, see Fig. 12, the surfaces of the cylinders 7 are provided below the blank portions thereof with numbers representing the values of the corresponding stops and sub-denominations, and, preferably, the surfaces of the cylinders are provided at uniformly placed intervals with numbers representing the successive multiples of the steps and sub-denominations. Any suitable means may be provided to turn the cylinders so as to present these numbers to view when the corresponding deposit keys are actuated. As shown, each of the cylinders is provided on its hub with a ratchet wheel 175 which is adapted to be engaged by a pawl 176 pivotally mounted on the corresponding deposit key 2 below the pivot thereof. The cylinder 7 is held at the point to which it is turned by means of a detent 177 which for convenience is pivotally mounted on the arm 151, 130

- see Figs. 7 and 9. For the purpose of releasing the actuated cylinder 7 to permit it to return to its normal position after each operation of the machine the detents 177 are provided with rearwardly extending arms adapted to be engaged by the cross bar 168 of the frame 165. When it happens that a deposit key is actuated which corresponds to one of the cylinders 7 which was actuated to indicate the result of the preceding operation, it is necessary that that cylinder should first be returned to normal position and then, turned one step farther to indicate the value corresponding to the actuated key. This is accomplished by causing the setting bar 156 to perform its function during the first part of the stroke of the deposit key and causing the pawl 176 to perform its function during the latter part of the stroke of the key.
- With this object in view, the links 158 are made extensible as above explained so that when the arms 157 strike the stops 162, the levers 159 together with the deposit key may continue to move. The pawls 176 are normally out of engagement with the ratchets 175 so that during the first part of the movement of the deposit keys the cylinders 7 are not moved by the pawls. In accordance with the construction shown, the pawls 176 are extended below their pivots so as to engage the stationary transverse bar 178 fixed at a suitable point below the pivot bar 160 of the deposit keys. To hold the pawls in contact with the bar 178 so that their movements will be controlled thereby at all times the pawls may be provided with suitable tension springs 179. It follows from this construction that each of the cylinders 7 will be advanced one step by each actuation of the corresponding deposit key and that if the cylinders 7 had been used in indicating the result of a previous operation, it will be advanced two steps by the first actuation of a deposit key, one step by the universal bar 156, and one by the corresponding pawl 176.
- Where the result giving means is constructed to both indicate the result of a computation or other operation of the machine and also to indicate an amount of money received, it is desirable that the machine be provided with a suitable movable sign to show what is indicated on the result giving means. In accordance with the embodiment of the invention illustrated a cylinder 180 is suitably journaled opposite the opening 181 in the front wall of the casing above the opening 9. For the purpose of automatically turning the cylinder so as to alternately exhibit two signs thereon, one having the words "Amount of change" or similar words, and the other having the words "Amount received" or similar words, the cylinder 180 is mounted on a shaft 182 (see Figs. 8 and 13), which is journaled at its opposite ends in the plates 92 and 93. The
- shaft 182 is provided near one end with a disk 183 having a shoulder adapted to engage a fixed stop pin 184. A spring 185 having one end connected to the shaft and the other end to the casing tends to keep the shoulder on the disk in contact with the pin 184. When the shaft is in this position, the sign "Amount of change" is in view. For the purpose of automatically turning the shaft whenever a deposit key is actuated so as to present the sign "Amount received" one of the levers 159 is provided with a rearwardly extending arm 186 (see Fig. 8) which is pivotally connected to a vertical push bar 187 so guided at its upper end as to strike a pin 188 fixed at a suitable point on the disk 183. For the purpose of holding the cylinder in the position to which it is moved by the actuation of a deposit key the disk 183 is provided with a locking shoulder adapted to be engaged by a detent lever 189 pivotally mounted at a suitable point on the plate 92. Near the end of the operation of the machine the cylinder 180 is released to again bring into view the sign "Amount of change" by cam 190 on shaft 23, said cam being arranged to strike a stud on the link 191, and to act through said link to release the detent lever 189. Where the result giving means serves merely to indicate the result, as in the machine illustrated in Figs. 1 to 15, a suitable cash receptacle is preferably provided, the same being normally locked and automatically released at the end of the operation of the machine so that the operator may select the pieces of money indicated on the result giving means. In accordance with the construction shown, see Figs. 2, 5, 7, and 8, a cash drawer 195 is mounted in the lower part of the casing 1, the same being normally locked in the casing by means of a pair of hooks 196 which are mounted on a pivot shaft 197 in position to engage the rear wall of the drawer. To release the hooks the shaft 197 is provided with an arm 198 which lies in the path of a cam 199 fixed on the shaft 23. The hooks 196 are normally held in position to engage the rear end of the cash drawer by arms 200 which are engaged by pins on a pair of spring controlled slides 201, see Fig. 5. The cash drawer is preferably projected when released, by a spring impelled plunger 202.
- The mechanism so far described is that serving to make computations involving two numbers. It is desirable however in a machine of this character to perform certain other operations. In a machine for computing change, for instance, it is desirable that the machine may be operated also to indicate amounts of money to be paid out. With this object in view the connecting means between the number indicating means and the result giving means is provided with an additional member which is rendered operative

- when it is desired to indicate on the machine an amount of money paid out, all other members of the connecting means being at the same time rendered inoperative.
- 5 As shown, the "paying out" member of the connecting means consists of a set of sliding bars for each numerical place of the machine. As there is only one key for the lowest numerical place of the machine shown, there is only one "paying out" bar 3° for that place. The set of "paying out" bars corresponding to the second numerical place includes a bar 4° for each element of the result giving means corresponding to 10 that place; the set corresponding to the third numerical place consists of a bar 5° for each element of the result giving means in that place; and the set corresponding to the fourth numerical place consists of a bar 6° 15 for each element of the result giving means in that place. These sets of "paying out" bars are normally inoperative, each set being rendered operative when any one key of the corresponding section of the deposit 20 keys is actuated. The means for rendering operative the respective sets of paying out connections may be and for convenience are rendered operative by the respective sections of the set controlling locking devices for the 25 main sets of connections. That is to say, the bar 3° corresponding to the units order may be rendered operative by the locking plate 25 which is operated from the key 3, the bar 3° being to that end provided with a projection 30 at a point opposite the front edge of the plate 25. The set 4° of paying out bars may be controlled in a similar manner by the locking plate 38 which is operated by any one of the keys 4. The paying out bars 5° 35 may be rendered operative by the locking plate 48 which is operated by any one of the keys 5; and the paying out bars 6° may be rendered operative by the locking plate 58 which is operated from any one of the keys 6. 40 Certain of the operative set or sets of the paying out bars must be rendered inoperative according to which of the keys of the corresponding section have been actuated. For the sake of convenience this auxiliary 45 control of the paid out bars is effected by the same locking devices which effect the auxiliary control of the main bars, the paying out bars being to that end provided with projections adapted to coöperate with the 50 auxiliary locking plates 80, 84, and 86.
- Any suitable means may be provided for the purpose of rendering the system of paying out connections operative and at the same time rendering inoperative the main 55 system of connections. In accordance with the construction shown, a pair of rock shafts 205 and 206 are arranged beneath the system of connections, said shafts being journaled in the frame sections 27, 28, and 29. 60 These shafts are connected to oscillate in unison by means of suitable gears, there being as shown, Figs. 2 and 4, two pairs 207 and 208, one pair on each end of the shafts. Each of the shafts is provided with locking plates extending throughout the entire system of connections, the shaft 205 having affixed thereon the plates 209 and 210 and the shaft 206 having fixed thereon the plates 211 and 212. In accordance with the construction shown, the plates on the shaft 205 70 serve to lock the paying out system of tumblers, while the plates on the shaft 206 serve to lock the regular system of tumblers. To this end the plates on the shaft 205 are normally in locking position and the plates on the shaft 206 are normally out of locking position. 75
- Any suitable means may be provided for actuating the shafts 205 and 206 for throwing the paying out system of connections into operation. As it is desirable to have a sign showing that the number indicated on the result giving means represents an amount of money paid out, the means for rendering the paying out system of operations operative are preferably connected and operated by such a sign. As it is preferable to have this sign replace the other signs for showing what the number indicated in the result giving means represents, the paying out sign is preferably carried by the cylinder 180, means being provided for shifting that cylinder so as to bring the paying out sign into view when it is desired to operate the machine to pay out money. In accordance with the construction shown, (see Figs. 13, 14 and 15,) the cylinder 180 is adjustably mounted on the shaft 182. Any suitable means may be provided for adjusting the cylinder on the shaft. The means shown, 80 see Figs. 13, 14, and 15, consists of a thumb wheel 215 mounted to slide longitudinally on one end of the shaft 182, said wheel being held at one limit of its movement by a compression spring 216 confined between 85 a head on the end of the shaft and a shoulder on the wheel. The wheel 215 is provided with a pin 217 which projects through a slot 218 in a collar 219 fixed on the shaft 182 and also through a perforation in a disk 220 affixed to the cylinder and then through one of two perforations in a collar 221 fixed on the shaft 182. The slot 218 corresponds in length to the distance between the perforations and the collar 221. By pulling the 90 thumb wheel 215 outwardly so as to release the pin 217 from one of the perforations of the collar 221 the thumb wheel together with the disk 220 and the cylinder 180 connected thereto may be readily turned to bring the pin 217 into alignment with the other perforations in the collar 221, the cylinder being thus shifted through a sufficient distance to bring the paying out sign thereon 95 into view. As the deposit keys are not actu- 100

- 110
- 115
- 120
- 125
- 130

ated during the paying out operation the cylinder 180 remains in its adjusted position until the machine is again used for computing change.

The shafts 205 and 206 for controlling the paying out connections may be operated from the cylinder 180 by any suitable means. As shown, see Figs. 8 and 13, the cylinder 180 is provided with a cam 222 which is arranged to move a push bar 223 when the cylinder 180 is adjusted to bring the paying out sign into view. The push bar 223 is pivotally connected at its rear end to one end of a vertical lever 224. The lever 224 is fixed to a pivot shaft 225 journaled in the frame plates 92 and 93 and is pivotally connected at its lower end to a link 226 which is connected to an arm 227 on the shaft 206, see Fig. 4. The shaft 225 is provided near the end and opposite the lever 224 with a depending arm 224^a which is connected by a second link 226 with another arm 227 at the opposite end of the shaft 206.

When the machine is used for paying out money, it is desirable to have the deposit keys locked so as to prevent improper operation of the machine. With this object in view the bar 223 is provided with a depending arm 228, see Fig. 8, which is connected to a sliding bolt 229 adapted to engage a locking recess in the push bar 187. It is also desirable that means be provided in a machine of the character described for indicating the amounts of the purchases. Any suitable indicating means may be provided for this purpose. In accordance with the construction shown, a series of indicating cylinders 233 is provided, one cylinder for each numerical place of the machine, said cylinders being for convenience located at the top of the casing to the rear of the sign cylinder 180 as shown. These cylinders are provided at regular intervals around their circumferences with numerals 1 to 9 and 0 in the usual manner and the front wall of the casing is provided with openings 234 through which numbers on the cylinders may be viewed. Each of the cylinders 233 is provided with a pinion 235 which meshes with a rack cut in a vertical sliding bar 236. The bars 236 are provided at their lower ends with racks adapted to mesh with pinions 237, see Fig. 6. The pinions 237 have clutch faces adapted to mesh with corresponding clutch faces formed on a set of pinions 238 which are engaged by racks cut in horizontal bars 239 which are arranged beneath and in line with the pivoted yokes 89^a of the respective rows of purchase keys. These bars (see Fig. 2) are provided with upwardly projecting lugs which are uniformly spaced apart and adapted to engage the yokes 89^a of the keys, which are also uniformly spaced. Each of the registering cylinders 233 is operated by the move-

ment of one of the bars 239 through the interposition of its rack, pinion 238, bar 236 having a rack at each end, and pinion 235 secured to the indicating cylinder. In order to have the numeral on the cylinder, corresponding to the depressed key, appear at the window it is necessary to provide a graduated movement of the bar 239, the movements differing for each numerical key. The depression of the 1 key should move the bar forward a unit's length or a distance equal to the pitch of the pinion 238, so that the pinion will be rotated the distance of one tooth when the 1 key is depressed, thus rotating the cylinder so as to bring the numeral 1 at the window. If the 7 key is depressed bar 239 should move seven units' length in order to rotate cylinder 233 so as to bring numeral 7 at the window. This is accomplished by making the spacings between key yokes 89^a equal to the spacings between the lugs, plus the unit movement of the bar, i. e., plus the pitch of the pinion 238; and by placing the first lug of the bar a unit's distance from the yoke of the 1 key. By this spacing and relative positioning of the yokes and lugs, each succeeding yoke will be one unit's distance farther from its lug than the preceding yoke is from its lug. Thus the 3 key will be three units in advance of its lug and the 4 key will be four units in advance of its lug, etc.: so that if the 2 key is depressed the bar will travel two units' length, causing the indicating cylinder to rotate so as to bring numeral 2 at the window. If the 7 key is depressed, the bar will travel seven units' length, causing the pinion to turn a correspondingly greater part of a revolution, so as to bring the numeral 7 at the window, and so on. Due to the fact that the spacing distance between adjacent yokes is less than the spacing distance between adjacent lugs, the distance between yokes will overlap the distance between lugs to the extent of a complete space before the sequence of numbers has run out, which makes it necessary to stagger the lugs, having one on one side of the bar 239 and the next on the other side of the bar, etc., and alternately cut away the front of the successive yokes as shown in Fig. 44. If this was not done the yoke of the key 8 when depressed would engage the lug for the 7 key, in which case the bar would not move at all; and the yoke for the 9 key when depressed would engage the lug for the 8 key, permitting the bar 239 to move only one unit's length as will be seen from an inspection of Fig. 2. Each of the bars 239 is provided also with an upwardly projecting lug adapted to engage the transverse bar 18, springs 240 being provided to move the bars rearward until stopped by engagement of their lugs with the yokes 89^a, when they are permitted to

move by the bar 18. The indicating cylinders 233 are released and permitted to return to their normal position before the bars 239 are permitted to move by a trip device 5 consisting of an arm 241 (see Fig. 5) fixed on the shaft 242 of the pinions 238 and adapted to be engaged by a pin 243 on the shaft 21. The shaft 242 is normally held in direction to engage the clutch members of 10 the pinions 237 and 238 by means of a spring 244. During the first part of the rotation of the shaft 21 the arm 241 is moved by the pin 243 in a direction to release the clutches between the pinions 237 and 238 and 15 thus permit the cylinders 233 to return to their normal positions. During the continued movement of the shaft 21 the bars 239 are permitted to move rearward and the clutches 237 and 238 being then engaged the 20 indicators 233 will be set according to the new operation.

For the purpose of indicating and continuously adding or summing up the amounts of the purchase prices indicated on 25 the machine a set of indicating cylinders 245 is provided, (best shown in Figs. 2 and 6,) the same being mounted on a shaft 250 near the lower end of the casing 1. Each of 30 these cylinders is provided with a ratchet which is engaged by a pawl carried by a pinion 251, which for convenience is arranged to mesh with a rack cut at the lower end of one of the bars 236. Backward movement of the indicating cylinders 245 is prevented by the detents 252.

When the machine is being used for computing change it is desirable that the purchase keys be locked until the deposit keys have been operated. To this end suitable 40 locking means are provided. In accordance with the construction shown, see Figs. 2, 7, 8, and 12, a vertically moving transverse frame is provided, said frame consisting of a pair of vertical bars 255 mounted to slide 45 vertically at opposite sides of the machine in pairs of lugs 256 and 257 projecting inwardly from the opposite frame plates 92 and 93. The bars 255 are connected by transverse bars 258 and 259 and the frame 50 is normally held in its uppermost position by means of compression springs 260 confined between the heads of the bars 255 and the lugs 256. The heads of the bars 255 are arranged in line with the universal bar 161 55 of the deposit key mechanism so that whenever any one of the deposit keys is actuated the locking frame will be moved downwardly. When the locking frame is depressed, it will be retained in its lower position 60 by a suitable catch, that shown consisting of the spring pressed sliding bars 201 which are suitably retracted so as to snap behind shoulders formed on the lower ends of the bars 255 when in their lowermost positions. As best shown in Figs. 7 and 8

transverse bar 259 of this frame is arranged when in its upper position to engage suitable recesses formed in the rear ends of the locking bars 89 for the respective rows of purchase keys, and the transverse bar 258 70 is located in the path of lugs formed on the recorder bars 239.

As the deposit keys are not actuated when the machine is used for paying out money, means must be provided for releasing the 75 purchase keys when the machine is set for paying out money. In accordance with the construction shown, this is accomplished by providing the bars 255 with inclined surfaces 261 adapted to be engaged by pins 262 80 carried by the links 226. For the purpose of releasing the purchase keys the locking bars 89 are retracted by suitable means after the result giving means has been actuated to present the result of an operation. As 85 shown in Figs. 2 and 5, the sleeve 123 is provided with a series of cam projections 89^a adapted to engage the ends of the bars 89 when said sleeve is actuated by cam 114^a to reset the locking devices on shafts 102 and 90 131. It is desirable also that the shaft by which the motion of the parts is produced or controlled be locked until after the purchase keys have been actuated. This may be accomplished by any suitable means. In accordance with the construction shown, the rear ends of the locking bars 89 for the respective rows of purchase keys are provided with cam surfaces 265 (see Fig. 71) adapted to engage a corresponding series of 100 arms 266 fixed on a transverse shaft 267. This shaft is provided at a suitable point with a yoke 268 which is adapted to embrace a locking disk 269 on the shaft 23. One arm of the yoke is provided with a hook adapted to 105 engage a suitable shoulder on the disk 269 so as to prevent forward movement of the shaft until the yoke has been moved out of locking engagement with the disk by the movement of one or more of the locking 110 bars 89. In order that the disk 269 may remain unlocked when it has been released by the yoke 268 the locking hook of the yoke is pivoted in such a manner that after being raised above the shoulder it will be retracted so as to rest on the disk above the shoulder leaving the disk and shaft 23 free to turn. When the disk 269 has been released by the yoke the opposite arm of the 115 yoke will be thrown into the path of the projection on the disk so that before the shaft 23 has made a complete revolution the yoke will be thrown back to its locking position.

The operation of the machine for computing change is as follows: The piece or pieces of money which are tendered for the payment of a purchase are indicated on the deposit keys 2 by depressing such of those keys as represent the values of the piece or 125 130

pieces of money received. If more than two pieces of one value are received, the corresponding key is depressed once for each piece. The amount of the purchase is then indicated on the purchase key board by depressing the keys representing the figures of the number by which the purchase price is expressed, due regard being had to the respective numerical orders of the figures of that number. The actuation of the deposit keys will have operated the three sets of locking devices located on the shafts 91, 102, and 131 above the system of connecting bars. The actuation of these keys will also have set the sign cylinder 180 to present to view the "Amount received" sign and will have set the cylinders 7 to indicate the amount of money received. The actuation of the deposit keys will also release the locking bars 89 so that the purchase keys can be actuated, and also the purchase price indicator actuating bars 239. The actuation of the purchase keys will have set the two systems of locking devices operated by them, said locking devices being normally held in their locking positions by the locking of the actuated keys. The actuation of the purchase keys moreover will have released the main shaft 23 of the machine. The operator then rotates the shaft 23 through one revolution, the motion of this shaft being communicated to the shaft 21. The first part of the revolution of the shafts 23 and 21 will permit the connecting bars which have not been locked to move rearward so as to set the corresponding dogs 171. The cams 171 will then act to lift the frame 165 and release certain of the detents 153 and all of the detents 177. This will permit all of the cylinders 7 which have been operated by the actuation of the deposit keys to return to normal inoperative position and will render operative the cylinders 7 corresponding to the actuated detents 153 to indicate the result of the computation. At the same time the sign cylinder 180 will be released to present to view the sign "Amounts of change." In the meantime the bars 239 will have moved rearward and actuated the indicator cylinders 233 and the indicating cylinders 245. During the latter part of the revolution of the shafts 23 and 21 the connecting bars and the indicating bars will be returned to their normal positions by the action of cams 20, the locking bars 89 for the purchase keys will be moved to release said keys by cams 89; the oscillators on the shaft 102, if either of them has been actuated, will be released by the same cam; the alternators on the shaft 131, if not in their normal positions will be turned to their normal positions by the same cam; the locking devices 90 will be returned to their inoperative positions by cam 190 and sliding bar 191, and the locking frame 255 is re-

leased and permitted to return to its normal operative position and the cash drawer is released by cam 199.

When the machine is used for paying out money the cylinder 180 is adjusted by means of the thumb wheel 215 to present to view the sign "Paying out," this operation serving through the action of links 226, to release the paying out sets of connections and to lock all other sets of connections, and at the same time to release, by the action of the cam, 261 and pins 262, the purchase key locking bars 89, as it is not desirable that amounts paid out be indicated with the amounts of the purchases. The movement of the frame 255 by the operation of the paying out device, is not sufficient to release the indicating bars 239. The amount of money to be paid out is indicated on the purchase keys by depressing the proper keys to indicate the number representing the amount to be paid out. Then the shaft 23 is rotated as before, the operation of the various parts being so far as they go the same as those previously described.

In the embodiment of the invention illustrated in Figs. 16 to 19 inclusive money receptacles are provided in which amounts of money received in payment of purchases may be deposited and from which amounts of money constituting the difference between the amounts received and the purchase amounts are delivered automatically by the machine. In accordance with the construction shown all parts of the mechanism used in the embodiment of the invention previously described except those parts relating to the cash drawer are also employed in the present embodiment of the invention. Only such parts of this mechanism therefore as are necessary to an understanding of the money receiving and discharging devices will be described. The money receiving devices consist of a series of wheels 270 one corresponding to each of the indicating cylinders 7. These wheels are loosely mounted on the shaft 8 adjacent to the corresponding cylinders 7 and they are provided in their peripheries with open-ended money receiving pockets adapted to receive coins or folded bills. The hub of each of these money receiving wheels is provided on its side adjacent to the corresponding wheel 7 with a ratchet wheel 271 having the same diameter and number of teeth as the ratchet wheels 175 of the cylinders 7. The pawls 176 are provided with broad faces (see Fig. 19) adapted to engage both the ratchet wheels 175 and 271 so that when the indicating cylinder is turned to present to view the number corresponding to the operated deposit key the pocket in which the money has been deposited will be moved from in front of the opening 9 in the casing so as to prevent the money therein from being re-

5 moved. Each of the money receptacles is retained in the position to which it is moved by a detent spring 272, the detent springs for all the receptacles being mounted on a transverse bar 273 fixed in the frame adjacent to the money receptacles. For the purpose of delivering the amount of money constituting the change between an amount received and a purchase price means are provided for rendering the actuated connecting bars effective for returning the corresponding money receptacles so as to present one of the filled pockets thereof to the opening 9 in the casing. In accordance with the construction shown this is accomplished by extending the dogs 171 upwardly beyond the point of their connection with the transverse bar 167 of the sliding frame 165 and providing their upper ends with suitable pawls 274 adapted to engage the partitions between the money pockets of the money receptacles. The rearward movement of any one of the connecting bars will have the effect of throwing the pawl 274 on the corresponding dog into position to engage a partition of the corresponding money receptacle. Upon the upward movement of the frame 165 the pawl 274 will then act to turn the receptacle one step backward.

10 With the object in view of preventing backward movement of the money receptacles at all times excepting by the operation of the pawls 274, the detents 153 are made wide enough to engage the money receptacles and are provided with a tooth adapted to engage recesses formed in the periphery of the money receptacles, opposite each of the pockets therein. For the purpose of ejecting the money from the receptacle which is opposite the opening 9 in the casing, the money receptacles are centrally slotted so as to receive a series of ejecting fingers 275, the same being mounted on a transverse shaft 276 which for convenience is located below the money receptacles and is provided with an arm 277 having a pin and slot connection with the vertical reciprocating bar 191. As the receptacles at times will receive more money than is delivered from them, means are provided to receive the money from the receptacles when a certain number of the pockets thereof have been filled. As shown, a cash receiving drawer 278 is mounted to slide transversely to the machine beneath the series of money receptacles. When the pockets filled with money arrive at a point above this drawer the money therein will be dropped out into the drawer. To prevent the money from dropping out of the pockets before they reach a position above the drawer suitable retaining guides 279 are provided, said guides as shown consisting of suitable wires 279 fixed to a transverse bar and located in the outer portions of the slots in the money receptacles. To insure the dis-

charge of the money into the drawer 278 a series of ejectors 280 similar to the ejectors 275 are provided, said ejectors as shown being mounted on the shaft 281 and suitably operated from the bar 191. The operation of this embodiment of the invention being substantially the same as that of the embodiment previously described will not require further description.

15 The principles involved in the construction and arrangement of the various sets of connecting bars may be readily understood by referring to the diagrammatic views Figs. 20 to 35. In the diagrammatic views the deposit keys of the machine are represented by the row of circles 2 and the purchase keys are represented by the respective rows of numbered circles 3, 4, and 5, the result giving means being indicated by the row of squares 7. The connecting bars are represented by the vertical lines, the units set being designated by the reference character 3^a, the tens set by 4^a, and the hundreds set by 5^a. The locking devices operated by the units purchase keys 3 and rendering operative the units set of connections and rendering inoperative the other sets of connections are represented by the lines 25 and 31. The locking devices operated by the tens keys 4 and rendering operative the tens sets 4^a of connections are represented by the lines 38 and 31 and the locking device operated by the keys 5 and rendering operative the hundreds set 5^a of connections, is represented by the line 48. The auxiliary locking devices corresponding to the respective key sections 3, 4, and 5 are represented by the lines 79, 80, and 84. The black dots at the intersections of the lines representing the connecting bars and the locking devices, indicate that the bars are normally locked by the locking devices but are released when the locking devices are actuated. The circles indicate that the bars are normally free but that the actuation of the locking device on which the circles appear will lock the connecting bars at those points. The cross marks, Figs. 26 and 30, indicate that it is immaterial whether the bars are locked or unlocked at those points. As the two locking devices by which one set of connections is rendered operative and the other set or sets in the same numerical place are rendered inoperative, are so connected in the machine as to be practically one part; the locking plates 25 and 68 or 31 and 67 for instance, the two devices are combined in a single line in the diagrams, the dots on such a line being located on the connecting bars which are normally locked and the circles on those bars which are normally unlocked but which are locked by the operation of the locking device.

20 Where the machine is used for computing change the actuation of any one of the de-

50 deposit keys in one numerical place locks all the connecting bars corresponding to that place and all those corresponding to the higher places, the auxiliary locking device 50 corresponding to each numerical place being actuated by any one of the keys in the corresponding place.

51 In a machine for mechanically performing the operations of subtraction, the resulting 51 giving means need not contain more elements or steps than enough to present the value represented by each numerical place of the machine less one of its units or steps, and any operative set of connections need 52 not include more elements than enough to enable the result-giving means to present the number of units or steps less one of each numerical place throughout which the operative set of connections extends. For 53 the sake of clearness, the principles involved in a machine for computing change will first be described in connection with a simple decimal monetary system, that is, a system in which each denomination is one-tenth of the next higher denomination, and in which there are no sub-denominations, as above defined; a system, for instance, having denominations corresponding to the pennies, dimes and dollars of United States 54 system. Such a mechanism is diagrammatically illustrated in Fig. 20.

55 In order that this machine may subtract the smallest amount, to wit, one cent, from the largest amount represented by the deposit keys, as well as to compute all intermediate amounts, the result giving means includes in each denominational section enough elements to represent the value of that denomination less one unit. As the 56 steps in each denomination are made up of the units of that denomination nine steps or elements are required in each denominational section of the result giving means and each set of connections includes one element for 57 each step in each denomination throughout which the set extends. For the purpose of causing the result giving means to present in each numerical place a certain number of the elements of that place depending 58 upon how many units or steps are to be subtracted in a given computation from that numerical place, the auxiliary locking devices operated by the purchase keys are effective to render inoperative certain of the 59 operative set of connections according to the value represented by the respective keys. In a machine for computing change the auxiliary locking devices in the lowest numerical place throughout which an operative set 60 of connections extends, render inoperative a number of connections corresponding to the value represented by the corresponding keys less one unit or step. In any numerical place above the lowest place throughout 61 which an operative set of connections ex-

tends, the number of connections rendered inoperative by the auxiliary locking devices corresponds in the values represented by them to the full number of steps represented by the corresponding purchase keys, the 70 reason being that whenever an amount is subtracted from a lower numerical place in computing change, the result giving means must present one less unit in each higher numerical place. The auxiliary locking device 79 operated by the "9" key of the units set 3, for instance, is effective to lock eight of the units set 3^a of connecting bars of the lowest numerical place of the machine; the auxiliary locking device operated by the "8" key locks seven connections; the auxiliary locking device for the "3" key locks two, etc. In like manner the auxiliary locking devices for the "9" key of the second numerical place locks eight of the tens set 85 4^a of connections; the auxiliary locking device of the "8" key locks seven, etc. The same is true of the auxiliary locking devices for the keys 5 of the third numerical place with respect to the hundreds set 5^a 90 of connections. The auxiliary locking device for the "9" key of each of the higher numerical places renders inoperative all of the connections of the units set 3^a in that place, the "8" key eight of them, etc. The auxiliary connections for the "9" key of the hundreds place renders inoperative all the connections of the tens set 4^a in that place; the "8" key eight of them, etc. It will be understood of course that the auxiliary locking devices are rendered effective for locking certain bars of the various sets by providing said bars with projections adapted to be engaged by the auxiliary locking devices, the relative locations of said 100 locking projections on the various bars being indicated by the circles in the diagrammatic views. These same general principles apply to a machine designed to manipulate a monetary system which although decimal 110 in character involves sub-denominations which are multiples of the units of the corresponding denominations. Certain additional principles are involved however to enable such a machine to correctly compute 115 the change when an amount of money received in payment of a purchase includes certain sub-denominations and certain combinations of the sub-denominations, the same being herein termed respectively irregular value elements and irregular combinations of value elements.

120 In Figs. 21, 22, 23, and 24 is diagrammatically illustrated a machine adapted to manipulate a monetary system having values 125 corresponding to the pennies, five-cent pieces, dimes, twenty-cent pieces and fifty-cent pieces of the United States system. The deposit keys 2 include, in each numerical section of the machine, a key represent- 130

ing each sub-denomination corresponding to that place together with enough keys representing the units of that place to make up a total representing the value of that place less one unit. Thus, there are four keys representing pennies, one key representing the five-cent piece, these keys corresponding to the first numerical place of the machine. In the second numerical place there are two keys representing dimes, one the twenty-cent piece, and one the fifty-cent piece. The units set 3^a of connecting bars includes a number for each step and sub-denomination of the result giving means in each numerical place. The tens set 4^a includes a number for each step and sub-denomination in the second numerical place. The set controlling locking devices 25 and 38 are arranged as in the first two numerical places of the machine diagrammatically illustrated in Fig. 20. One locking device 90 is provided for the one-cent deposit keys, another for the five-cent deposit key, another for the two ten-cent deposit keys, another for the twenty-cent deposit key, and another for the fifty-cent deposit key. In arranging for the locking of the bars by the auxiliary locking devices 79 and 80 the numerical values represented by the respective connecting bars are taken into consideration. In order that the machine may indicate the result in the pieces of the largest possible value the rule is generally observed that the auxiliary locking devices are made effective so far as possible for locking the bars corresponding to the steps or sub-denominations of the lower values rather than the sub-denominations of the higher values. The auxiliary locking device for the "3" key of the 4^a set, for instance, is arranged to render inoperative the two bars corresponding to the ten-cent pieces rather than to render inoperative the bar corresponding to the twenty-cent piece. The construction diagrammatically illustrated in Fig. 21 will correctly compute the change for any purchase price provided the amount of change required is not more than ninety-nine cents and that the money tendered in payment does not include one or more twenty-cent pieces or a combination of one or an odd number of fifty-cent pieces and one or more twenty-cent pieces, it being understood of course that the purchase price in each case is greater than the sum of all pieces of money except one of the lowest value. The twenty-cent piece in this form of the machine constitutes an irregular value element and combinations of one or an odd number of fifty-cent pieces and one or more twenty-cent pieces constitute irregular combinations of value elements and amounts involving them will not be correctly computed by the regular sets of connections.

65 In order to compute proper change for the

deposit of a twenty-cent piece or a number of twenty-cent pieces an auxiliary set of connections is necessary. This auxiliary set of connections together with the main connections necessary to compute change for a deposit of a twenty-cent piece or a number of twenty-cent pieces is diagrammatically illustrated in Fig. 22, all parts of the machine not involved in such a computation being omitted. The first numerical place of this part of the machine is precisely the same as that of Fig. 21. As the greatest amount of change required for any purchase price under twenty cents is nineteen cents and as nine cents are supplied by the first numerical place of the machine, the only amount ever required from the second numerical place is ten cents. The auxiliary set of connections therefore is that required to control one of the elements of the result giving means corresponding to the ten-cent pieces.

By reason of the fact that some of the purchase prices will require the operation of the units keys 3, and some only the tens keys 90 4, two auxiliary connecting bars 3²⁰ and 4²⁰ are provided, one of said bars, 3²⁰, being normally locked by the locking device 25 and the other, 4²⁰, by the locking device 38, the bar normally locked by the device 38 95 being locked when the locking device 25 is actuated. These bars correspond therefore respectively to the units bars 3^a and the tens bars 4^a of the main sets. The effect of the auxiliary locking devices 80 on the auxiliary 100 set of bars is determined by considering the change required for various purchases. For instance, the purchase being ten cents, the "1" key of section 4 is depressed, thus rendering operative the bar 4²⁰. The change 105 required for this price being a dime the bar 4²⁰ is not locked by the auxiliary locking device of the "1" key and the dime is presented by the result giving means. The price being eleven cents, the "1" key of the 110 section 4 is depressed together with the "1" key of the section 3. This will render operative the bar 3²⁰ and as a dime is not required in making the change for this price the auxiliary locking device for the "1" key 115 of the 4 section will lock the bar 3²⁰. If the purchase price is twenty cents the "2" key of the 4 section will be alone depressed, and the bar 4²⁰ will be rendered operative. No change being required the auxiliary locking 120 device for this key will lock the bar 4²⁰. Where the purchase price is twenty-one cents and two twenty cent pieces are deposited, the "2" key of the section 4 will be depressed together with the "1" key of the 125 section 3, thus rendering operative the bar 3²⁰. As a dime is required in the change the auxiliary locking device for the "2" key will not lock the bar 3²⁰. If the purchase price is thirty cents, and two twenty cent 130

pieces are received the "3" key of section 4 is alone depressed, thus rendering operative the bar 4²⁰. As a dime is required in the change the auxiliary locking devices for the 5 "3" key will not lock the bar 4²⁰. If the purchase price is thirty-one cents, the "3" key of the section 4 will be depressed together with the "1" key of section 3, thus rendering operative the bar 3²⁰. As no dime 10 is required in the change the auxiliary locking device for the "3" key will lock the bar 3²⁰. By following this process out it will be found that the bar 3²⁰ will be locked by the auxiliary locking devices for the odd keys 15 of section 4 and will not be locked by the auxiliary locking devices for the even keys of the section 4; whereas the bar 4²⁰ will not be locked by the auxiliary locking devices for the odd keys of section 4 and will be 20 locked by the auxiliary locking devices for the even keys of section 4.

The auxiliary set of connections required to make proper change from an amount received including irregular combinations of 25 a fifty-cent piece or any odd number of fifty-cent pieces and one or more twenty-cent pieces is diagrammatically illustrated in Fig. 23. In this figure the connections and locking devices for the first numerical place 30 of the machine are the same as in the two previous figures. As the amount of change required from any deposit including a twenty-cent piece is always less than twenty cents, the auxiliary connections for the combination of one or more twenties with the 35 fifty do not have to extend to more than one of the elements of the result giving means corresponding to the ten cent pieces. The auxiliary set for the twenty-cent piece however will not serve for making change for the twenty-cent pieces when combined with a fifty or any odd number of fifties, for the reason that the sum of such a combination always ends in an odd number of tens as 70, 40 90, 110, 170, 190, etc.; whereas the sum of 45 any number of twenty-cent pieces always ends in an even number of tens, as 40, 60, 80, etc.

Referring to the diagram, Fig. 23, the 50 auxiliary bars for the twenty-fifty combination are marked 3⁵⁰ and 4⁵⁰ said bars being controlled by the locking device 25 in the same manner as the auxiliary bars 3²⁰ and 4²⁰. The effect of the locking device 38 will 55 be explained below. Supposing now the purchase price to be fifty-one cents and a fifty-cent piece and a twenty-cent piece to have been received. The change required is nineteen cents. The "5" key of the 60 section and the "1" key of the 3 section having been depressed, nine cents will be presented by the result giving means corresponding to the first numerical place of the machine, and ten cents will be required in the second

numerical place. The operative bar 3⁵⁰ 65 therefore will not be locked by the auxiliary locking devices for the "5" key of the 4 section. Assuming the purchase price to be sixty cents, the "6" key of the 4 section will be alone depressed and the bar 4⁵⁰ will be 70 rendered operative. As the change required is ten cents the auxiliary locking device for the "6" key will not lock the 4⁵⁰ bar. Assuming the price to be sixty-one cents the "6" key of the 4 section and the "1" key of 75 the 3 section will be depressed and the bar 3⁵⁰ will be rendered operative. As the change required is only nine cents, however, the bar 3⁵⁰ will be locked by the auxiliary locking device for the "6" key of the 4 section. Assuming the purchase price to be seventy cents, the "7" key of the 4 section will be alone depressed and the bar 4⁵⁰ rendered operative. As no change is required, however, the auxiliary locking device for the "7" key will 80 lock the bar 4⁵⁰. Assuming now that the purchase price is a dollar and ten cents and the amount received includes a fifty cent piece and three twenty-cent pieces, the "1" key of the 4 section being depressed together 85 with the "1" key of the 5 section, the bar 4⁵⁰ will be rendered operative, but as no change is required the auxiliary device for the "1" key will lock the bar 4⁵⁰. Following 90 out this process it is found that the bar 3⁵⁰ will not be locked by the auxiliary locking devices for the odd keys of the 4 section and that it will be locked by the auxiliary locking devices for the even keys of the 4 section; whereas, the bar 4⁵⁰ will be locked 95 by the auxiliary locking devices for the odd keys of the 4 section and not locked by the auxiliary locking devices for the even keys of the 4 section.

There is a class of the fifty-twenty combinations which are not taken care of by the auxiliary set of bars 3⁵⁰, 4⁵⁰ as thus far described. The class of combinations referred to are those amounting to a dollar and ten cents, two dollars and ten cents, three dollars and ten cents, etc., and one of the difficulties encountered arises when the purchase prices are one, two and three dollars respectively. Thus assuming an amount received to be a fifty-cent piece and three twenty-cent pieces and the purchase to be one dollar, the change required is ten cents. The "1" key of section 5 will be alone depressed. If the bar 4⁵⁰ be normally locked by the locking device 38, there will be no connection available to give 110 the required change. This difficulty might be overcome by providing for the ten-cent piece an extra connection in this auxiliary set, which connection is unlocked when the fifty and twenty-cent deposit keys have been 115 actuated, but is locked by the actuation of either of the locking devices 25 and 38. It is found, however, that the bar 4⁵⁰ does not 120 125

require to be normally locked by the locking device 38, the reason being that except for the particular class of fifty-twenty combinations now being considered some key in section 4 is actuated for every purchase, so that the effect of the 4⁵⁰ connection is taken care of by the auxiliary locking devices 80. This connection, therefore, may be and is made effective to present the change required for 10 the combinations and purchase prices referred to, by simply omitting the locking connection between it and the locking device 38. Another difficulty with this class of combinations arises when the purchase 15 prices are between one dollar and one dollar and ten cents, two dollars and two dollars and ten cents, etc. In this case unless the 3⁵⁰ connection is not normally locked by the locking device 38 it will be rendered operative and the change presented will be ten cents too great. This difficulty may be overcome, however, by causing the locking device 38 to normally lock the 3⁵⁰ connection, as, for the purchase prices corresponding to all 20 other fifty-twenty combinations, some key in section 4 is operated, thus unlocking the 3⁵⁰ connection and controlling it by the auxiliary locking device 80.

To make the machine diagrammatically 30 illustrated in Fig. 21 operative to correctly compute the change for amounts received including twenty-cent pieces and combinations of twenty-cent pieces and fifty-cent pieces it is only necessary to combine the auxiliary sets of connections 3²⁰, 4²⁰, and 3⁵⁰, 4⁵⁰ with the main sets illustrated in Fig. 21, said auxiliary sets being rendered operative by the actuation of the deposit keys 20 and 50 respectively; the main sets corresponding 40 to the dimes in the second numerical place of the machine being at the same time rendered inoperative. This construction is diagrammatically illustrated in Fig. 24.

The auxiliary locking devices for rendering operative the auxiliary sets 3²⁰, 4²⁰ are diagrammatically illustrated by the line 102, the same serving to normally lock the auxiliary set 3²⁰, 4²⁰, and also the auxiliary set 3⁵⁰, 4⁵⁰, and when actuated to unlock said auxiliary sets and to lock the members of the main sets 3²⁰ and 4²⁰ corresponding to the ten-cent pieces. The locking device 102 is so connected to the twenty-cent deposit key as to be actuated whenever that key is actuated. The auxiliary locking device for the auxiliary sets 3⁵⁰, 4⁵⁰ is represented by the line 123, said locking device serving to normally lock the auxiliary set 3⁵⁰, 4⁵⁰, and when actuated to unlock said set and lock 60 the auxiliary set 3²⁰, 4²⁰. This locking device is so connected to the fifty cent deposit key however that it is only actuated on the first actuation of said key and on each alternate actuation of said key as the auxiliary set of

connections 3⁵⁰, 4⁵⁰ are only required when one or more twenty-cent pieces are combined with a fifty-cent piece or with an odd number of fifty-cent pieces.

Where a sub-denomination is not a multiple of the unit of its numerical place a further principle of construction is required to render the machine capable of making correct change from such sub-denomination and combinations of such sub-denominations with certain other pieces of money. Where an amount received in payment of a purchase includes a single piece of money of such irregular sub-denomination or a number of pieces of money of such sub-denominations or irregular combinations of such sub-denominations with other pieces the sum of which pieces or combinations is not divisible by the units of the corresponding numerical place, an auxiliary set or sets of connections are required to enable the machine to make the correct computations. It is necessary, moreover, to include in the result giving means corresponding to the numerical places of such sub-denominations such element representing values less than the unit of that numerical place as are required to enable the successive steps of that numerical place to be presented by the result giving means.

To enable a machine to correctly compute change from the twenty-five cent piece of the United States monetary system, for instance, auxiliary sets of connections corresponding to the ten-cent deposit keys and the twenty-cent deposit key are required and it is required to include in the second numerical place of the result giving means one or more elements representing the five-cent pieces. One form of machine, including means for correctly computing change for one or an odd number of twenty-five cent pieces and for one or an odd number of twenty-five cent pieces combined with one or more ten cent pieces, is diagrammatically illustrated in Figs. 25, 26, 27 and 28. In Fig. 25 so much of the machine is diagrammatically illustrated as is required to make correct change from any piece or combination of pieces of money except one or an odd number of twenty-five cent pieces, one or more ten cent pieces and combinations of one or an odd number of twenty-five cent pieces with one or more ten cent pieces or any combination including said pieces provided that the change required does not exceed 99 cents. The first numerical place of this diagram is precisely the same as the first numerical place of the diagrams last described. The second numerical place of this machine, however, includes sub-denominations and steps representing a total value of ninety-five cents instead of ninety cents, there being provided two five cent deposit

keys, one ten-cent deposit key, one twenty-five cent deposit key, and one fifty-cent deposit key, and corresponding elements in the result giving means. The units and tens sets of connecting bars include one bar for each of the elements of the second numerical place and these bars are locked and unlocked by the locking device 25 in the same way as the bars in the second numerical place are locked and unlocked in the machine previously described. The locking 38 operated by section 4 of the purchase keys normally locks the bars 4^a of the second numerical place as in the previous machine and it also normally locks the bars 3^a corresponding to the extra five-cent element in the numerical place, so that when the units set 3^a of connections is rendered operative without operating any key in the section 4 there will only be rendered operative enough connections in the second numerical place to deliver the number of units represented by that place less one, that is to say, ninety cents. Whenever any one of the keys of section 4 is operated the number of connections of the 4^a set will be greater than that required to deliver nine of the units of that place, but the extra connection is taken care of by the auxiliary locking device for the operated key of that section. In fixing the operation of the auxiliary locking devices for the keys of section 4 the same rule is observed as that laid down in describing the previous machine; that is to say, the auxiliary locking device for each key locks all the bars 4^a except those corresponding to an element or elements of the result giving means which represent the difference between the number of the key and the total number of elements represented by the second numerical place, and it locks such of the bars 3^a as represent a value one unit greater than the value represented by the locked bars 4^a.

The auxiliary set of connecting bars and such of the main set of connecting bars as are required to compute the change from one or an odd number of twenty-five cent pieces are diagrammatically illustrated in Fig. 26. The only elements required to make change for all purchase amounts under twenty-five cents are the four one-cent elements of the first numerical place of the machine and the two five-cent elements and the ten-cent element of the second numerical place. All these elements are required to make the change for all purchases up to five cents. For purchases from five cents to ten cents the elements required are the four one-cent elements of the first numerical place and the ten cent and one of the five-cent elements of the second numerical place. To make the proper change under these circumstances the set controlling locking device 25 is divided into three sections, one section 25^{a1} being operated only by

keys 1 to 5, inclusive, of the units keys 3, another section 25^{a2} being operated only by the keys 6 to 9, inclusive, of the units keys 3, the main section 25 being operated by all of the keys of the 3 set. The locking section 25^{a1} normally locks three of the auxiliary set of connecting bars in the second numerical place, said bars corresponding to the ten-cent and the two five-cent elements of the result giving means. These three bars are designated by the number 3²⁵⁻¹. The auxiliary locking device 25^{a2} normally locks two of the auxiliary set of connections, said two bars corresponding to the ten and one of the five-cent elements of the result giving means. These two bars are designated by the number 3²⁵⁻². The locking section 25 normally locks the four connecting bars corresponding to the one-cent elements of the first numerical place and when actuated locks two bars of the auxiliary set of connections, said bars corresponding to the ten cent and one of the five-cent elements of the second numerical place. These latter two bars are referred to by the number 4²⁵. The bars 4²⁵ are normally locked by the locking device 38 corresponding to the section 4 of the purchase keys. It follows from this construction that whenever one of the units keys 3 is actuated, the set 3^a of connections of the first numerical place is rendered operative and the bars 4²⁵ of the auxiliary set are rendered inoperative and one or the other of the auxiliary bars 3²⁵⁻¹ or 3²⁵⁻² is rendered operative depending upon whether the actuated units key 3 is in the 1 to 5 section or the 6 to 9 section. The locking effect of the auxiliary locking devices 79 for the units key 3 on the units set 3^a of connections is the same as it is on the corresponding members of the 3^a set in the first numerical place of the diagram Fig. 25. The locking effect of the auxiliary locking devices 80 for the tens keys 4 is determined by a consideration of the change required for various purchase prices under twenty-five cents, and of the various purchase prices between fifty and seventy-five cents. Assuming that a twenty-five cent piece is received and that the purchase price is one-cent, the "1" key of the units row 3 is depressed. This will render operative the 3^a set of connections in the first numerical place and the 3²⁵⁻¹ connections in the second numerical place. None of these connections being rendered inoperative by the auxiliary locking devices, the twenty-four cents required for change, a ten-cent piece, two five-cent pieces, and four cents, will be presented by the result giving means. Assuming now that the purchase price is six cents, the "6" key of the units row will be depressed, thus rendering operative the 3^a set of connections in the first numerical place and the 3²⁵⁻² connections in the second numerical place.

place. None of these connections being rendered inoperative by the auxiliary locking devices, one ten-cent piece, one five-cent piece, and four cents, will be presented by 5 the result giving means, which is the amount of change required. Assuming that the purchase price is ten cents, the "1" key of the 4 row will be depressed, thus rendering operative the connections 4^{25} in the second numerical place. As fifteen cents are required 10 in change, neither of these connections will be rendered inoperative by the locking device 80 of the said "1" key. Assuming now that the purchase price is eleven cents, the "1" key of both the rows 3 and 4 will be depressed, thus rendering operative the 3^a set of connections in the first numerical place and the 3^{25-1} set of connections in the second numerical place. As none of the 3^a 15 set is rendered inoperative by the auxiliary locking device 79 of the "1" key of the 3 row, four cents will be presented by the result giving means in the first numerical place. As fourteen cents are required in 20 change, the auxiliary locking devices 80 of the "1" key of the 4 row serve to lock the two connections 3^{25-1} corresponding to the two five-cent pieces of the second numerical place, the free 3^{25-1} connection serving to 25 present the ten-cent piece on the result giving means. Assuming now that the purchase price is sixteen cents, the "1" key of the 4 row is depressed together with the 6 key of the 3 row, the 3^a set of connections 30 of the first numerical place and the 3^{25-6} connections of the second numerical place being thus rendered operative. As none of the 3^a connections are locked by the auxiliary locking devices for the "6" key, four cents will 35 be presented by the first numerical place of the result giving means. As the change required is nine cents, the auxiliary locking devices for the "1" key serve to lock the bar 3^{25-6} corresponding to the ten-cent piece 40 and leaves the connection 3^{25-6} corresponding to the five-cent piece free to present five-cents on the result giving means. Assuming now that the purchase price is twenty cents, the "2" key of the 4 row is alone depressed 45 thus rendering the 4^{25} connections operative. As the change required is but five cents, the 4^{25} connection corresponding to the ten-cent piece is locked by the auxiliary locking device of the "2" key, the 4^{25} 50 connection for the five-cent piece being left free to present the five cents required. Assuming the purchase price to be twenty-one cents the "2" key of the 4 row is depressed together with the "1" key of the 3 row, thus rendering operative the 3^a set of connections in the first numerical place and the 3^{25-1} 55 connections in the second numerical place. As only four cents are required in change, the auxiliary locking device 80 of the "2" key serves to lock each of the con- 60

nctions 3^{25-1} . If the purchase price is twenty-five cents, the "2" key of the 4 row is depressed together with the "5" key of the 3 row. As the auxiliary locking device 79 of the "5" key locks the 3^a set of connections in the first numerical place, no change will be presented by the result giving means. As the change for a deposit of two twenty-five cent pieces is correctly computed by the regular sets of connections in Fig. 25 the auxiliary set of connections is not used. The locking effect of the auxiliary devices for the keys of the 4 row used in indicating purchase prices between fifty cents and seventy-five cents is determined in the same manner as the locking effect of the auxiliary locking devices for the keys used in indicating purchase prices under twenty-five cents. It will be seen that certain connections of the auxiliary set 85 of connections for the twenty-five cent piece, may or may not be locked by the auxiliary locking devices 80 for the 4 row of purchase keys. These points are marked with an X. 90

The auxiliary connections required for computing change where the amount of money received includes both a twenty-five cent piece and a ten-cent piece, or combinations of one or an odd number of twenty-five cent pieces with one or more ten cent pieces, are diagrammatically illustrated in Fig. 27. While never more than nine cents are required for making change for purchase prices between twenty-five cents and 100 thirty-five cents, or between thirty-five and forty-five, forty-five and fifty-five, etc., or between seventy-five and eighty-five, eighty-five and ninety-five, etc., the nine elements of the first numerical place of the machine, 105 as controlled for making change for purchase prices under ten cents or between ten cents and twenty cents, twenty cents and thirty cents, thirty cents and forty cents, etc., will not serve to correctly indicate the 110 change for the combinations of the twenty-five cent piece and the ten-cent piece. This will be apparent when it is considered that for making change from the ten-cent piece or multiples of the ten-cent piece, the five-cent piece together with one or more cents is required whenever the purchase price is under five cents and only pennies are required when the purchase price is above five cents; whereas, in making change from the 115 combinations of the twenty-five and ten-cent pieces only pennies are required when one key of the 1 to 5 section of the units key is actuated in indicating the purchase price and the five-cent piece together with pennies are required when a key of the 6 to 9 section of the units keys is actuated in indicating the purchase price. In making change from the combinations of the twenty-five and ten-cent pieces, therefore, the one- 120

cent elements of the first numerical place and one of the five-cent elements of the second numerical place are used. As the five-cent piece is only required when a key 5 of the 6 to 9 section of the units keys 3 is used, only two sections of the set controlling locking device 25 are used, to-wit, the section 25 which is actuated by both the sections of the units keys 3 and the set 25^a 10 actuated by the 6 to 9 section of the units keys 3. Only two auxiliary connections are required for one of the five-cent elements in the second numerical place, to-wit, the connection 3¹⁰⁻⁶ normally locked by the locking section 25^a and the connection 4¹⁰ locked by the actuation of the locking device 25. The auxiliary locking devices 74 for the 3 row of keys operate as in the previous diagrams. The auxiliary locking 20 devices 80 of the 4 row of keys are not required to lock either of the connections 3¹⁰⁻⁶ or 4¹⁰ as will readily be seen by a consideration of the various purchase prices between twenty-five cents and thirty-five cents, and 25 between thirty-five cents and forty-five cents, etc.

When the combination of the twenty-five and ten-cent pieces amounts to a dollar and five cents, two dollars and five cents, etc., 30 and the purchase price is a dollar, two dollars, etc., no key in either of the rows 3 and 4 will be actuated in indicating the purchase price, and yet five cents in change is required. This contingency may be provided for in various ways. A simple way 35 is to provide an additional auxiliary connection corresponding to one of the five-cent elements of the second numerical place and to have that element normally free 40 when the auxiliary set of connections for the twenty-five-ten-cent combination is in operation but to have it rendered inoperative when any key of either of the 3 or 4 rows is actuated. Preferably, however, this 45 contingency is provided for by not having the locking device 38 operate to lock the bar 4¹⁰, it being found this construction will not interfere with the correct computation of other change amounts.

50 The combination of the auxiliary connections of Figs. 26 and 27 with the main set of connections of Fig. 25 is diagrammatically illustrated in Fig. 28. In combining these sets of connections it is to be observed 55 that wherever the effects of the auxiliary locking devices for the various keys do not conflict with each other, the elements of the auxiliary sets of connections may be combined with the elements of the main sets of 60 connections and in determining whether or not the effects of the auxiliary locking devices conflict with each other as to the connections controlled thereby the fact is taken into consideration that it is immaterial 65 whether or not certain of the auxiliary lock-

ing devices act to lock certain of the auxiliary connections. Thus it is found, as indicated by the X marks, that the auxiliary locking devices 80 for the 2 and 7 keys of the 4 row may or may not lock either of the 70 auxiliary connections 3²⁵⁻⁶; the auxiliary locking devices for the "3", "4", "8", and "9" keys of the 4 row may or may not lock any one or all of the auxiliary connections for the twenty-five cent 75 piece; and the auxiliary locking devices for the "5" key of the 4 row may or may not lock the two connections 4²⁵.

Comparing the elements of the various sets of connecting bars it will be seen that 80 the 4²⁵ bar corresponding to the ten-cent piece must not be locked by the auxiliary locking devices for the "1" and "6" keys of the 4 row and it must be locked by the auxiliary locking devices for the "2" and 85 "7" keys of the 4 row. In Fig. 25 it is found that the 4¹⁰ connection for the ten-cent piece fulfills these conditions. These two connecting bars therefore may be combined and are combined in the diagram 90 of Fig. 28. It is seen also that the bar 4²⁵ corresponding to the five-cent piece, Fig. 26, must not be locked by auxiliary locking devices of the "1", "2", "6" and "7" keys of the 4 row; and that it is immaterial 95 whether said bar is or is not locked by the auxiliary locking devices of the "3", "4", "5", "8" and "9" keys of the 4 row. This bar, therefore, may be combined with the 4^a bar for the second five-cent piece, Fig. 100 25, as bar 4^a is only locked by the "3", "4", and "9" keys of the 4 row. It is found, furthermore, that the 3²⁵⁻⁶ bar corresponding to the five-cent piece is not locked by any of the auxiliary locking devices of 105 the keys of the 4 row. This is also true of the bar 3¹⁰⁻⁶. These bars therefore may be combined in the complete machine and they are combined in the diagram of Fig. 28.

For the purpose of controlling the auxiliary sets of connections the ten and twenty-five cent deposit keys are provided 110 with auxiliary locking devices. As the auxiliary set of connections for the twenty-five-cent piece is rendered operative in the first, third, fifth, etc., operations of the twenty-five cent deposit key and is rendered inoperative on the second, fourth, and following even operations of the deposit key 115 the locking device for the twenty-five-cent key is so connected therewith as to be operated on the first and alternate operations of the key and to be returned to normal on the second and even operations of the key. It will be seen that this auxiliary locking device normally locks all of the auxiliary 120 set for the twenty-five-cent piece except the 4²⁵ bars for the ten-cent piece and the second five-cent piece which bars are combined 125 with the main set of bars, and normally 130

locks the 4¹⁰ bar of the auxiliary set for the ten-cent piece. When actuated, it releases these auxiliary bars and locks all of the main sets of connections in the second 5 numerical place of the machine below the twenty-five cent piece except the ones which are combined with the 4²⁵ bars and it also locks the bar of the units set 3^a corresponding to the five cent piece of the first numerical place, these bars not being used in 10 computing change for the twenty-five cent piece. The auxiliary locking device for the ten-cent deposit key is always rendered operative when that key is actuated. This device 15 normally locks the bar 4¹⁰ and, when actuated, releases that bar and locks all bars of the main sets in the second numerical place of the machine below the ten cent piece and also locks all the twenty-five cent 20 set except the one which is combined with the 3¹⁰⁻⁶ bar of the ten-cent set.

In the place of having the sections 1 to 5 and 6 to 9 of the units keys 3 separately 25 control the elements of the auxiliary connections in a machine for computing change for irregular pieces of money, as the twenty-five cent piece of the United States monetary system, the locking sections 25^{a1} and 25^{a2} controlled by the respective key sections 30 may be made to control all connections of the units set throughout the numerical places involved in making such change.

In accordance with the principles of the construction, each element throughout the 35 set of connections corresponding to the divided row of keys may be divided into as many independently controllable parts as there are sections in the divided row of keys, each part being controlled by the corresponding sections of keys. It is preferable, however, to so divide only those elements which correspond to the elements of the result giving means representing the 40 irregular piece of money and the pieces of lower value in the same numerical place. Such a construction is diagrammatically 45 illustrated in Figs. 29 and 30, which represent the first two numerical places of a form of the machine for manipulating U. S. 50 money including the twenty-five-cent piece. In accordance with this construction the first numerical place includes only the four pennies, the five-cent piece being transferred to the second numerical place. In the particular construction shown the second numerical place includes elements corresponding to one fifty-cent, one twenty-five-cent, one ten-cent and two five-cent pieces, ninety-five cents in all. The 1 to 5 section of the 55 60 row of keys actuates a locking section 25^{a1} which normally locks the elements 3^{a1} of the units set of connections, which elements 3^{a1} correspond to the twenty-five-cent, the ten-cent and the two five-cent elements of 65 the result giving means. The section 6 to 9

of the 3 row of keys operates a locking section 25^{a2} which normally locks the 3^{a2} elements of the units set of connections, which elements correspond to the same elements of the result giving means as the 3^{a1} elements. The locking device 25 which as before is operated by each of the units keys 70 75 80 85 90 95 100 105 110 115 120 125 130 3 serves to normally lock all the elements of the units set of connections except those which are divided and when actuated to lock the tens set 4^a in the second place. If all the connections of the units set in the first two numerical places were divided, the locking devices 25 would not be required, each of the sections 25^{a1} and 25^{a2} being made to lock the tens set 4^a in the tens place. The locking device 38 for the 4 row of keys normally locks the 4^a set of connections in the tens place as in the forms of the machine previously described. The locking device 38 also normally locks the 3^{a2} connections for one of the five-cent pieces, as only ninety of the ninety-five cents in the tens place are required when one of the 6 to 9 section of the 3 row of keys has been actuated. The connections corresponding to the pennies are controlled by the auxiliary locking devices 79 of the units keys 3 in the same manner as in the forms previously described. The auxiliary locking devices 80 of the tens keys 4, however, operate somewhat differently than in the previous forms of the machine. In determining the effects of the locking devices 80 on the 3^{a1} set of connections the fact is taken into consideration that, in addition to the regular amount supplied in the tens place, five cents must be supplied for the units place. Otherwise the same rules are followed as in the previous forms of the machine. The auxiliary locking device 80 of the "9" key, for instance, locks all the tens set of connections in the tens place except the 4^a bar corresponding to the ten-cent pieces and also all the units set of connections in the tens place except the 3^{a1} bar corresponding to one of the five-cent pieces. The locking device 80 of the "8" key leaves operative enough of the tens set of connections to present twenty cents on the result giving means, enough of the units set 3^{a1} to present fifteen cents, and enough of the units set 3^{a2} to present ten cents. The locking device 80 of the "7" key leaves operative enough of the tens set of connections to present thirty cents, enough of the units set 3^{a1} to present twenty-five cents and enough of the set 3^{a2} to present twenty cents, and so on. It is found that this form of the machine as so far described will within its capacity, correctly compute the change for the twenty-five-cent pieces as well as for all other pieces and combinations of pieces; except one or more ten cent pieces and combinations of one or more ten-cent pieces with other pieces.

This will be made apparent by trying out the various purchase prices under twenty-five cents, between fifty and seventy-five cents, etc., on the diagram, Fig. 29, or by comparing the auxiliary set of connections for the twenty-five-cent piece as diagrammatically illustrated in Fig. 30. This auxiliary set includes a bar 3^{25-1} for the ten-cent and two for the two and five-cent pieces; a bar 3^{25-6} for the ten-cent and one for one of the five-cent pieces; and a bar 4^{25} for the ten-cent and one for one of the five-cent pieces. By considering the various purchase prices under twenty-five cents, between fifty and seventy-five cents, between one dollar and one dollar and twenty-five cents, etc., it will be found that the various bars of the auxiliary set must be locked by the auxiliary locking devices 80 at the points denoted by circles, that the bars must be left open at the points not marked and that they may or may not be locked at the points marked with an X. Now comparing these bars with the corresponding part of Fig. 29 it will be seen that the locking effects of the device 80 do not interfere so that the auxiliary set may be combined with and wholly composed of the bars of the main sets. To enable this form of the machine to make change for the ten-cent piece and combinations of the ten-cent piece with any piece of higher value except the twenty-five-cent piece, it is only necessary to provide for one of the five-cent pieces, a connection 3^{10-1} which is only rendered operative by the combined action of the ten-cent deposit key and any one of the 1 to 5 section of the units keys 3, and at the same time to render inoperative the other connections for the five-cent pieces. This is accomplished by having the bar normally locked by the locking section 25^{a1} and by the locking device 102 and by constructing the device 102 when actuated to lock those bars of the main sets which correspond to the five-cent pieces.

To enable the machine to compute correctly the change for any combination of the twenty-five-cent and ten-cent pieces the sum of which ends with the numeral 5, as 35, 45, 85, etc., a connection must be provided which will present the extra five cents with the 6 to 9 section of the units keys 3 instead of with the 1 to 5 section. This connection marked 3^{10-6} , therefore, must be rendered operative with the combined actuation of the twenty-five-cent and ten-cent deposit keys and any one of the 6 to 9 section of the units keys, the bar 3^{10-1} being at the same time rendered inoperative. To accomplish this the bar 3^{10-1} is locked by the first and alternate actuations of the locking device 123 of the twenty-five-cent deposit key and the bar 3^{10-6} is unlocked by the second and alternate actuations of the device

123 and by each actuation of the locking device 102 of the ten-cent deposit key. Except for one class of combinations the bar 3^{10-6} might be normally locked by the locking section 25^{a6} so as to be unlocked by the actuation of any one of the 6 to 9 section of the units keys 3. To supply the change required when the twenty-five-ten combination amounts to a dollar and five cents, two dollars and five cents, etc., and the purchase price is respectively one dollar, two dollars, etc., and at the same time to cut out the extra five cents when the respective purchase prices are between one dollar and one dollar and five cents, two dollars and two dollars and five cents, etc., the bar 3^{10-6} is not affected by the locking section 25^{a6} but is locked by the actuation of the locking section 25^{a1} .

The construction diagrammatically illustrated in Fig. 29 will correctly compute the change for the five-cent piece and for any combination of pieces including the five-cent piece, as is apparent when it is noted that all connections except those corresponding to the pennies are rendered inoperative by the auxiliary locking device 90 for the five-cent deposit keys 2.

While the ten-cent and the two five-cent pieces are all that are required to make change with and for the twenty-five cent piece, it is desirable to employ instead two ten-cent pieces and one five-cent piece, so that whenever pieces amounting to twenty cents are required in the change, two dimes can be presented in place of one dime and two five-cent pieces. Such a form of one machine is diagrammatically illustrated in Fig. 31. This construction involves the same principles as the construction illustrated in Figs. 29 and 30 and need not be specifically described further than to point out that, in determining the effect of the locking device 38 and the auxiliary locking devices 80, the fact that the elements of the tens section of the result giving means represent a total of one dollar in place of ninety-five cents.

To adapt any form of the machine to present change for any piece of money received without indicating thereon a purchase price it is only necessary to add another unit element to the lowest numerical place of the result giving means, normally lock the corresponding connection 3^a by the set controlling locking device 25, lock said connection by the actuation of each of the auxiliary locking devices of the units keys and provide means for actuating the locking device 25 independently of the purchase keys. The first numerical place of such a machine is diagrammatically illustrated in Fig. 32, the key marked "C" being provided to actuate the locking device 25 independently of the keys 3 to make change. Where an irregular piece of money, as the twenty-five-cent

piece of the U. S. money is used, the change key "C" is also connected to the locking section corresponding to the last division of the keys 3, as the section 25th, since this is the 5 only set controlling locking device which will give the required number of units in the tens place.

Where it is desired that a machine shall manipulate nothing less than the five-cent 10 piece, the units section 3 of the purchase keys includes only the "5" key and the element of the result giving means corresponding to the five-cent piece of the units place. Where the twenty-five-cent piece is used in this 15 form of machine, moreover, it is not necessary to divide any of the elements of the units set of connections as in the constructions shown in Figs. 29, 30, and 31. The first two numerical places of such a machine 20 are diagrammatically illustrated in Fig. 33. In accordance with the construction shown, the members of the units and tens sets of connections 3rd and 4th in the second numerical place are respectively controlled by the 25 locking devices 25 and 38 in the same manner as in the form of the machine illustrated in Figs. 21 to 24 inclusive. In determining the effect of the auxiliary locking devices 80 on the units and tens sets of connections the 30 fact is taken into consideration that a total of one dollar is represented by the elements of the tens section of the result giving means and that, when the units set of connections is rendered operative, five cents less is required 35 in the second numerical place than when the tens set of connections is rendered operative.

The machine as thus far described will correctly compute the change for all pieces 40 and combinations of pieces of money except the ten-cent piece and combinations including the ten-cent piece. To enable the machine to compute change for the ten-cent piece, an additional five-cent element is provided, the same being, for convenience, located in the units place of the machine, and the connection for this element is rendered operative only by the combined actuation of a ten-cent deposit key and the "5" key 3. 45 This connection 3rd, when rendered operative, will present five cents on the result giving means and this is the only change that is ever required, when the amount of money received includes a ten-cent piece. This 3rd connection however will not present the proper 50 change when the sum of a combination of one or more ten-cent pieces with one or more twenty-five-cent pieces ends with the numeral 5, as, for instance, 35 cents, 45 cents, 55 85 cents, etc. To take care of this class of combinations another connection 4th is provided, said connection being rendered operative by the combined effect of either the ten-cent deposit key and one or an odd number 60 of actuations of the twenty-five-cent de-

posit key, but is locked by the actuation of the "5" key 3, as no change is required when the "5" key is operated with such a combination. This bar 4th will also take care of the ten-twenty-five combinations, the sums 70 of which amount to a dollar and five cents, two dollars and five cents, etc. Since this auxiliary bar is rendered operative with the tens set of connections 4th and also with the hundred set of connections 5th, as required 75 to take care of the special class of combinations referred to, it is marked 4th and 5th. To enable this form of the machine to present the change for any piece of money received, it is only necessary to connect the 80 change key "C" to the set controlling locking device 38 since this locking device presents the full value of both the units and tens numerical places of the machine.

For the purpose of enabling the machine 85 to pay out any amount of money which may be indicated on the purchase keys, an extra system of connections, herein termed the "paying out" connections, is provided. One 90 system of paying out connections is diagrammatically illustrated in Fig. 34, three numerical places of a machine adapted to manipulate pieces of money from one-cent to five dollars being shown. In accordance with this construction the system of paying 95 out connections includes a set for each numerical place of the machine, each set being rendered operative by any one of the keys of the corresponding numerical place, and certain of the operative set being rendered 100 inoperative by the auxiliary locking devices of the corresponding set of keys. In determining the effect of the auxiliary locking devices the fact is taken into consideration that those elements of the result giving 105 means are to be rendered operative which represent the value of the actuated key. The auxiliary locking device 79 of the "9" key of the first numerical place, for instance, must render operative sufficient of the 3rd 110 connections to present in the first numerical place of the result giving means nine cents, that is a five-cent piece and four one-cent pieces; the auxiliary locking device for the "8" key renders operative those of the 3rd 115 connections corresponding to the five-cent piece and three one-cent pieces, etc. The auxiliary locking devices 80 of the "9" key of the 4th row render operative the 4th connections corresponding to the fifty-cent 120 piece, the twenty-five-cent piece, one of the ten-cent pieces, and the five-cent piece, making ninety cents in all; the auxiliary locking device of the "8" key renders operative the 4th connections corresponding to the fifty-cent piece, the twenty-five-cent piece, and one of the five-cent pieces, making a 125 total of eighty cents, etc. The auxiliary locking device 94 of the "9" key of the 5th row renders operative all of the 5th connections in 130

the hundreds place, as only nine units of that place are included in the hundreds section of the result giving means. The auxiliary device of the "8" key of the 5 row 5 renders operative the 5^p connections corresponding to the five dollar bill, the two-dollar bill, and one-dollar bill, making a total of eight dollars; when the "7" key is actuated, the five-dollar bill and the two-dollar bill are presented by the result giving 10 means, etc.

In Fig. 35 the various features and principles set forth in connection with the previous diagrams are combined in a single 15 construction, this diagram representing the machine shown in detail in Figs. 1 to 19, inclusive. It will be seen that this machine includes the first three numerical places and two elements of the forth numerical place. 20 This machine is designed to manipulate no pieces of money of a lower value than the five-cent piece, and it also includes a paying out system of connections. The first and second numerical places are the same as the 25 numerical places diagrammatically illustrated in Fig. 33 combined with the paying out sets of connections 3^p and 4^p. The construction forming the third numerical place of this machine is precisely the same in 30 principle as that forming the second numerical place of the form of the machine diagrammatically illustrated in Fig. 24, the connections required to compute the change for the two-dollar bill and the combination 35 of the two-dollar with one or an odd number of five-dollar bills being precisely the same as those required for computing the change for the twenty-cent piece and the combination of the twenty-cent piece with one or an 40 odd number of fifty-cent pieces. The third numerical place of the machine of Fig. 35 also includes the hundreds set 5^p of paying out connections, there being one connection for each element of the hundreds section of 45 the result giving means.

As the twenty-dollar bill is never presented by the result giving means in computing change, the system of change computing connections only extends to the ten-dollar element of the result giving means of the fourth place. The change computing connections in the fourth place consist of a 50 bar rendered operative with and forming a part of each of the units sets and hundreds 55 sets of connections, said bar being designated by the numbers 3^a, 4^a, and 5^a. These connections also include a bar 6^a which is the only element of the thousands set of connections in the machine shown. These two 60 bars are controlled by the set controlling locking devices in the same manner as the other bars of the corresponding sets and they are controlled by the auxiliary locking devices 86 of the 5 row of keys in the same 65 manner that the auxiliary set 8², 4², and 5²

for the two-dollar bill are controlled by the auxiliary locking devices 84 of the 5 row of keys.

In order that both the ten-dollar bill and the twenty-dollar bill may be paid out of the machine when no money has been received and no purchase price indicated, a paying out bar 6^p is provided for each of the elements of the result giving means in the fourth numerical place.

The principles of this invention may be applied to a machine for making computations with the mills denomination of the United States money as well as and in connection with the higher denominations. As 70 however a form of the machine adapted for making computations with the mills denomination in connection with the twenty-five-cent piece of the dimes denomination involves a minor principle of the invention 75 which has not heretofore been explained, such a form of machine will be explained, the same being diagrammatically illustrated in Fig. 36. The fact that this form of the machine includes a numerical place of a 80 lower order than the one which is divided into sections to enable the machine to correctly compute change for the irregular piece of money is what gives rise to the additional principle referred to. The difficulty arises 85 from the fact that in passing from one section to the other of the divided row of keys a different operation of the parts is required when a key of the lower denomination is 90 operated than when such denomination is 95 not used. In accordance with the construction shown the section of the purchase keys corresponding to the mills denomination is 100 designated by a 0; the set of connections corresponding to the mills denomination and 105 extending throughout all the numerical places of the machine is designated by 0^a; the set controlling locking device operated by the 0 keys is designated by 25^a; and the auxiliary locking devices of the 0 keys are 110 designated by 78. The sets of connections corresponding to the units and tens places and the set controlling and auxiliary locking devices controlled by the units and tens keys are designated by the same numbers as in 115 the previous diagrams wherein the units denomination is divided to compute correctly the change for the twenty-five-cent piece. It is noted, however, that the set controlling device 25 is operated by any one of the 3 120 row of keys is divided into two sections, the first section 25 extending only through the cents place, and the second section 25^a extending through the dimes place, it being so connected with the section 25 and the locking device 25^a that it may be operated by the latter device independently of the former.

It will be observed that whereas the cents set of connections in the tens numerical place is required to give a total of five cents less 130

than the tens set of connections in that place when any one of the 1 to 5 sections of the 3 rows of keys is actuated without actuating one of the 0 rows of keys, when the "5" key of the 3 row is actuated in connection with one of the 0 row of keys, the units set of connections of the tens place must present a total of ten cents less than the tens set of connections in that place. If, for instance, five cents is subtracted from one dollar, ninety-five cents will be the result; whereas, if five cents and one mill are subtracted from one dollar, ninety-four cents and nine mills will be the result. In the first case the units set of connections in the cents place and 3^{a1} connections of the units set in the tens place will be rendered operative, giving ninety-five cents in the dimes place and nothing in the cents place. In the second case the 0^a set of connections will be rendered operative and ninety-cents should be delivered in the tens place, four cents in the cents place, and nine mills in the mills place. The machine may be caused to give this result in various ways. In accordance with the best embodiment of the invention, however, the connections of the mills set in the tens place are divided in the same manner that the cents connections are divided in the tens place, and are controlled in the same manner as the cents connections are controlled by the locking sections 25^a and 25^b, and means are provided whereby the "5" key of the 3 row, when operated without operating any key in the 0 row, serves to actuate the locking section 25^a; whereas, when the "5" key in the 3 row is actuated in connection with one of the keys in the 0 row, the effect of the "5" key is transferred from the locking section 25^a to the locking section 25^b. Any suitable means may be employed for thus transferring the effect of the "5" key from one locking section to the other. One form of mechanism for accomplishing this result is illustrated in the detail views Figs. 37 and 38, Fig. 37 being a side elevation and Fig. 38 a plan view of the same. In accordance with the construction shown, 3^b represents the stem of the "5" key, 41^{a1} is the universal bar common to the 1 to 5 keys of the 3 row and serving to communicate their motion to the locking section 25^{a1}; 41^{a2} is the universal bar common to the 6 to 9 keys of the 3 row and serving to communicate their motion to the locking section 25^{a2}; 41^b is the universal bar by which the motion of the 0 row of keys is communicated to the locking device 25^b; 79 is the auxiliary locking device operated by the "5" key, said device having a dependent arm 79^a by which one or the other of the universal bars 41^{a1} and 41^{a2} may be actuated by the "5" key 3. In place of having the projections on the universal bars 41^{a1}, 41^{a2} by which the motion of the arm 79^a is trans-

mitted to them, rigidly formed on the bars, they are formed by the upwardly turned ends of a pair of pivoted levers 411 and 416, said levers being pivoted near their central points on the universal bars 41^{a1} and 41^{a2} respectively. The bar 41^b is provided with a centrally pivoted lever 410 having at one end a lateral section 410^a adapted to underlie both the universal bars 41^{a2} and 41^{a1}. The bar 41^{a2} is provided with a depending lug 416^a arranged slightly in advance of the lateral extension 410^a of the lever 410 when both of the universal bars 41^{a2} and 41^b are in their normal positions. The lever 410 at its upper left-hand end is arranged to be moved downwardly by a projection 310 on the stem of the "5" key so as to swing the lateral extension 410^a up in front of the lug 416^a on the bar 41^{a2}. The lower right-hand end of the lever 411 is so formed as to be engaged by the lateral extension 410^a of the lever 410 whether that lever has been operated by the extension 310 or not. The lower left-hand end of the lever 416 is so formed as to be normally engaged by a lateral extension 412 of the bar 41^b when both the bars 41^{a2} and 41^b are in their normal positions. It follows from this construction that when the universal bars are in their normal positions the bar 41^{a1} will be in operative connection with the "5" key and the bar 41^{a2} will be out of operative connection with said key, so that if the "5" key is actuated without actuating any of the keys of the 0 row the universal bar 41^{a1} will be actuated. If, however, any one of the keys of the 0 row is actuated the bar 41^{a2} will be actuated in place of the bar 41^{a1} and this result will be effected whether the key in the 0 row is actuated before or after the "5" key in the 3 row is actuated. If the "5" key is actuated first, the extension 410^a of the lever 410 will be thrown up in front of the lug 416^a, so that the movement of the bar 41^b will be transmitted to the bar 41^{a2} and at the same time the lever 411 will be operated to release the bar 41^{a1} from the actuating arm 79^a. If the key in the 0 row is operated before the "5" key of the 3 row, the extension 410^a of the lever 410 will render 411 inoperative and the arm 412 of the bar 41^b will render the lever 416 operative so that when the "5" key is actuated, the bar 41^{a2} will be moved instead of the bar 41^{a1}. It remains to be observed that in this machine when one of the keys of the 0 row is actuated without actuating any key in the 3 and 4 rows, ninety-five cents must be presented by the tens section of the result giving means and that when one of the keys of the 0 row is actuated in connection with one of the keys of the 4 row without actuating a key of the 3 row, five cents less must be presented by the tens section of the result

giving means than when the tens set of connection is rendered operative. This result may be conveniently accomplished by rendering the locking section 25^a operative with the locking device 25^c when any key is actuated in the 3 row. This may be accomplished in any suitable way. As shown, it is accomplished by providing the section 25^a with an arm 25^x, the motion of which is communicated to an arm 25^y on the locking section 25^{a1}, the connection between said arms being removed when it is desired to have the section 25^{a1} operated with the locking device 25^c. As these two locking devices may be operated together at all times except when the universal bar 41^{a6} is actuated the arms 25^x and 25^y are as shown connected by a member 25^z which is movably mounted on the bar 41^{a6} and is carried by the actuation of that bar out of the paths of the arms 25^x and 25^y.

The form of machine diagrammatically illustrated in Fig. 36 will be found to make correct computations with amounts involving the denominations represented. In order to adapt this machine to make computations with higher denominations it is only necessary to add the higher denominations to the denominations shown, the addition being made, for example, in the manner in which the higher denominations are added in Fig. 35 to the denominations shown in Fig. 33.

Instead of operating the connecting means of a machine constructed in accordance with this invention by the keys bearing the significant figures, the connecting means may be rendered operative in whole or in part by a special key or keys. Where, for instance, a member of the number indicating means is adapted to have abstract numbers indicated thereon in the Arabic notation, the connecting means may be controlled by one or more keys or elements representing the ciphers. Where the cipher or "0" keys are to be used for this purpose, consideration is given to the fact that the "0" key of any section of a member of the number indicating means representing an order of the number to be indicated on that member practically belongs to the keys bearing the significant figures of the section corresponding to the next higher order. Thus, the "0" key of each row is made to render operative the member of the connecting means corresponding to the row of keys of the next higher order. In the embodiment of the invention illustrated, for example, the tens set of connections may be rendered operative by an "0" key in the units row 3; the hundreds set by an "0" key in the tens row 4. In this construction the units set of connections might be normally operative, the same being rendered inoperative by the actuation of either of the "0" keys. If the units set of connections is to be normally inoperative, it

is controlled by the significant figures of the lowest numerical place or by the "0" key representing the first order below the decimal point. The first three-numerical places of a form of the machine constructed on the above principles are illustrated in Fig. 39. In accordance with this construction the locking device 25 for the units set 3^a of connections is rendered operative by the keys bearing the significant figures of the 3 row and this locking device 25 is connected to operate the locking section 31 of the third numerical place as in the previous forms of the machine. The locking device 38 for the tens set 4^a of connections in the second numerical place is connected with the "0" key of the 3 row, said locking device being normally connected to actuate the locking device 31 of the third numerical place as in the previous forms of the machine. The locking device 48 for the hundreds set of connections in the third numerical place is connected with the "0" key of the 4 row. As, however, the "0" key in the 3 row is always actuated when the "0" key in the 4 row is actuated, the latter key must serve also to render inoperative the tens set of connections in the second numerical place, as, except for certain special combinations of money received, there must be no connections operative in the lower numerical places, when no key bearing a significant figure in either of these places is actuated. The actuation of the "0" key in the 4 row, moreover, serves to disconnect the locking device 38 from the locking section 31 in the third numerical place, as otherwise, when the "0" keys in the two lower orders are actuated with a key bearing a significant figure in the third numerical place, the hundreds set of connections in that place would not be rendered operative as required. This result may be accomplished in any suitable way. As shown, the motion of the arm 38^x on the locking device 38 is conveyed to the arm 31^x on the locking section 31 by a movable member 38^y which is connected by a link to a crank 48^x on the locking device 48 so that when the locking device 48 is moved, the member 38^y will be moved out of the paths of the arms 38^x and 31^x. For the same reasons and in like manner the actuation of the "0" key of the 5 row serves to lock the elements of the main hundreds set of connections in the hundreds place and to disconnect the locking device 48 from the locking section 47 in the fourth numerical place.

While the construction diagrammatically illustrated in Fig. 39 includes four elements corresponding to the pennies of the United States money, one element corresponding to the five-cent piece in the first numerical place; one element corresponding to the ten-cent piece and four elements corresponding to the twenty-cent piece in the second nu-

merical place; and two elements corresponding to the dollar, coin or bill, one corresponding to the two dollar bill and one corresponding to the five-dollar bill in the hundreds place; it is obvious that this character of construction may be employed in connection with any elements and sub-denominations of money desired, the number and nature of the connections being varied in accordance with the principles explained in connection with the previous forms of the machine.

When it is not desired to have the set of connections corresponding to the lowest numerical place normally locked, the form of "0" key actuated set controlling locking devices diagrammatically illustrated in Fig. 40, may be used. In accordance with this construction the locking device 38 for the "0" key of the 3 row serves to lock the units set 3^a of connections in the first and second numerical places and to render operative the tens set of connections 4^a in the second numerical place. The locking device 48 of the "0" key of the 4 row serves, when actuated, to lock the tens set of connections 4^a in the tens place. The locking device 48 is divided into two sections, the section 48^a for the third numerical place being movable independently of the part 48 for the second place. To actuate the locking section 48^a of the third numerical place so as to render inoperative the bars forming parts of the units and tens set of connections and to render operative the bars forming the hundreds set of connections 5^a in the third numerical place the actuation of both the locking devices 38 and 48 is required. This may be accomplished in any suitable way. As shown, the locking devices 38 and 48 are each provided with an arm 38^x and 48^x, respectively, which engage opposite ends of a member 48^y, which is loosely pivoted at an intermediate point on an arm 48^x of the section 48^a. For a like purpose and in a similar manner the locking device actuated by the "0" key of the 5 row serves to lock the hundreds set of connections 5^a in the hundreds place and in conjunction with the locking section 48^a to actuate the main locking section for the next higher numerical place. It will be seen that the combined action of all three "0" keys of the units, tens, and hundreds places is required to render operative the thousands set of connections and to render inoperative the other set.

Instead of making up the various sets of connections corresponding to the respective numerical places of the machine partly of independent elements and partly of elements common to two or more sets, as in all forms of the machine so far described, each set of connections may be wholly made up of independent elements. Such a construction is diagrammatically illustrated in Fig. 41 in

which the first three numerical places of the machine are represented. In accordance with this construction there are provided for each element of the result giving means for the higher numerical places, as many 70 connecting bars of the main sets as represent the number of the numerical places. That is to say, the elements of the result giving means of the third numerical place will have three connecting bars each; those of the 75 fourth numerical place four connecting bars each, etc. The set controlling locking device 25 operated by any one of the keys of the 3 row extends throughout all the numerical 80 places of the machine and serves, when actuated, to render operative the units set 3^a of connections and to lock all other sets of connections. The locking device rendered operative by each of the keys of the 4 row extends throughout the second and all higher 85 numerical places and serves, when actuated, to render operative the tens set 4^a of connections, and to render inoperative all sets of connections of a higher order. The locking device 48 for the 5 row of keys extends 90 throughout the third and all higher numerical places and serves to render operative the hundreds set of connections 5^a and to render inoperative all sets of connections of a 95 higher order. The locking effect of the auxiliary locking devices for the respective rows of keys is determined on the same principles as those of the forms of the machine previously described.

While the construction shown in Fig. 41 100 is designed to manipulate pieces corresponding to the one-cent, five-cent, ten-cent, and twenty-cent pieces, and the one, two, and five-dollar bills of United States money, this form of construction may of course be arranged to manipulate any other pieces of money, auxiliary sets of connections such as those described in connection with previous diagrams being provided when necessary.

The set controlling locking devices of the 110 form of machine illustrated in Fig. 41 may be constructed to be operated by the "0" keys of the respective rows of keys instead of by the significant figure. Thus in Figs. 42 and 43 the set controlling locking devices 38, 48, and 58 which control respectively the tens, hundreds, and thousands sets of connections, are operated by the "0" keys of the units, tens, and hundreds rows 115 3, 4, and 5, instead of by the significant 120 figures of the tens, hundreds, and thousands rows 4, 5, and 6. In the construction illustrated in Fig. 43 the locking device 25 operated by the keys of the 3 row which bear significant figures and which locking device 125 normally locks the units set of connections, is not required, when actuated, to lock all sets of connections corresponding to the higher numerical places as in the form of the machine shown in Fig. 41. Each of 130

the locking devices 38 and 48 corresponding to the tens and hundreds sets of connections serves to normally lock all connections of a higher numerical place than that to which it belongs. Each of the locking devices 48 and 58 corresponding to the hundreds and thousands sets of connections serves, when actuated, moreover, to render inoperative the tens and hundreds connections, respectively. In Fig. 43 the locking device 25 is omitted, the units set of connections being normally operative. In accordance with this construction the locking device 38, which is operated by the "0" key of the units row 3 serves, when actuated, to render inoperative the units set of connections. In other respects the locking devices 38, 48, and 58 of this form of the machine are the same as those of the corresponding parts of the form of the machine diagrammatically illustrated in Fig. 42.

This invention in its broader aspects is not limited to the particular construction herein disclosed nor to any particular construction by which it may be carried into effect, as the construction in which the basic principles of the invention can be embodied may be varied between wide limits without departing from these principles and without sacrificing the chief advantages resulting from the use of this invention.

Having thus described my invention, what I claim, and desire to secure by Letters Patent, is:

1. In a computing machine the combination of number indicating means, means for giving the results of the computations, and connecting means between the number indicating means and the result giving means, said connecting means including a plurality of members, one member for each numerical place of the machine, each member of the connecting means composed of a series of movable parts extending through its own and all higher numerical places in the machine.

2. In a computing machine the combination of number indicating means, means for giving the results of the computations, and connecting means between the number indicating means and the result giving means, said connecting means including a plurality of members, one member for each numerical place of the machine, each member of the connecting means composed of a series of movable parts, the member corresponding to the lowest numerical place, in which a significant figure of the number indicating means is indicated being operative to present on the result giving means in each higher numerical place the value of such higher place less one of its units and in its own numerical place the value of that place less the number of its units represented by the significant figure indicated.

3. In a computing machine, the combination of number indicating means having a plurality of members on which numbers may be indicated, means for giving the results of the computations, and connecting means between the number indicating means and the result giving means, said connecting means including a member corresponding to each of the lower numerical places of the machine, each member being rendered operative by the significant figures of one member of the number indicating means in the corresponding place when no significant figure of a lower place has been indicated.

4. In a computing machine, the combination of number indicating means on which numbers may be indicated, means for giving the results of the computations, and connecting means between the number indicating means and the result giving means, said connecting means including a member corresponding to each of the lower numerical places of the machine, said connecting members being normally rendered inoperative and only the one of them which corresponds to the lowest numerical place in which a significant figure is indicated during any operation of the machine being rendered operative to give the results of the computations.

5. In a computing machine, the combination of number indicating means having a plurality of members on which numbers may be indicated, means for giving the results of the computations, and connecting means between the number indicating means and the result giving means, said connecting means including a member for each of the lower numerical places of the machine, said members being normally rendered inoperative and only the one of them corresponding to the lowest numerical place in which a significant figure of one member of the number indicating means has been indicated being rendered operative to present on the result giving means the results of the computations, the operating member being limited in its operation by the numbers indicated on another member of the number indicating means.

6. In a computing machine, the combination of number indicating means, means for giving the results of the computations, and connecting means between the number indicating means and the result giving means, said connecting means including a set of connections for each of the lower numerical places of the machine, each of said sets of connections being rendered operative by the significant figures of the number indicating means in the corresponding numerical place when no significant figure of a lower numerical place has been indicated.

7. In a computing machine, the combination of number indicating means having a

plurality of members on which numbers may be indicated, means for giving the results of the computations, and connecting means between the number indicating means and the 5 result giving means, said connecting means including a set of connections for each of the lower numerical places of the machine, said connecting means being normally locked and only the one of them corresponding to 10 the lowest numerical place in which a number has been indicated on one member of the number indicating means being rendered operative, parts of said operative set of connections being rendered inoperative by the 15 significant figures indicated on another member of the number indicating means.

8. In a computing machine, the combination of number indicating means having a plurality of members on which numbers may be indicated, means for giving the results of 20 the computations, and connecting means between the number indicating means and the result giving means, said connecting means including a set of connections for each of the 25 lower numerical places of the machine, the set of connections corresponding to the lowest numerical place in which a significant figure has been indicated being rendered operative by said significant figure and portions of the operative set of connections being rendered inoperative by the significant 30 figures of said member of the number indicating means which are in higher numerical places.

35 9. In a computing machine, the combination of number indicating means, means for giving the results of the computations, and connecting means between the number indicating means and the result giving means, 40 said connecting means including a member for each of the lower numerical places of the machine, the member corresponding to the lowest numerical place in which a significant figure is indicated on the number indicating means being operative to present 45 on the result giving means the results of the computations.

10. In a computing machine, the combination of number indicating means having 50 a plurality of members on which numbers may be indicated, means for giving the results of the computations, and connecting means between the number indicating means and the result giving means, said connecting 55 means including a member for each numerical place of the machine, one of said connecting members being rendered operative with the significant figures indicated on one member of the number indicating means.

60 11. In a computing machine, the combination of number indicating means having a plurality of members on which numbers may be indicated, means for giving the results of the computations, and connecting means 65 between the number indicating means and

the result giving means, said connecting means including a set of connections for each numerical place of the machine, one of said connecting members being rendered operative with the significant figures of one 70 member of the number indicating means.

12. In a computing machine, the combination of number indicating means having a plurality of members on which numbers may be indicated, means for giving the results of the computations, connecting means between the number indicating means and the result giving means, said connecting means including a set of connections for each numerical place of the machine, one of said 80 connecting members being rendered operative with the significant figures of one member of the number indicating means, and portions of the operative set of connections being rendered inoperative with the numbers indicated on another member of the number indicating means.

13. In a computing machine, the combination of number indicating means having a plurality of members on which numbers may be indicated, means for giving the results of 90 the computations, and connecting means between the number indicating means and the result giving means, said connecting means including a set of connections for each of the lower numerical places of the machine, each set of connections being rendered operative with the significant figures of one member of the number indicating means in the corresponding place when no significant 95 figure has been indicated in the lower numerical place.

14. In a computing machine, the combination of number indicating means having a plurality of members on which numbers may be indicated, means for giving the results of the computations, and connecting means between the number indicating means and the result giving means, said connecting means including a set of connections for 105 each of the lower numerical places in the machine, each set extending through its own numerical place and higher places and being rendered operative with the significant figures of one member of the number indicating means in the corresponding numerical place to present on the result giving means in each higher numerical place the value of such higher place less one of its units and in its own numerical place the 110 value of that place less the number of its units represented by the significant figure indicated.

15. In a computing machine, the combination of number indicating means, means for giving the results of the computations, and connecting means between the number indicating means and the result giving means, said connecting means including a 125 set of connections corresponding to each of 130

the lower numerical places of the machine, said sets being controlled by the significant figures of the number indicating means, the control of a set corresponding to a lower numerical place being different in a higher numerical place than that of the set corresponding to the higher place.

16. In a computing machine, the combination of number indicating means, means for giving the results of the computations, and connecting means between the number indicating means and the result giving means, said connecting means including a set of connections corresponding to each of the lower numerical places of the machine, said sets of connections being controlled by the significant figures of the number indicating means, the set of connections corresponding to a lower numerical place being controlled in a higher place to present on the result giving means one less unit of the higher numerical place than is presented by the set of connections corresponding to the higher place.

17. In a computing machine, the combination of number indicating means, means for giving the results of the computations, connecting means between the number indicating means and the result giving means, said connecting means including a set of independently movable elements corresponding to each of the lower numerical places of the machine, and means independent of the number indicating means for actuating said connecting means.

18. In a computing machine, the combination of number indicating means, means for giving the results of the computations, connecting means between the number indicating means and the result giving means, said connecting means including a set of connections controlled by the significant figures of the number indicating means in the lower numerical places of the machine to present in a higher place the value of the higher place less one of its units, and means independent of the number indicating means for actuating said connecting means.

19. In a computing machine, the combination of a number indicating means, means for giving the results of the computations, and connecting means between the number indicating means and the result giving means, said connecting means including a set of connections corresponding to each of the lower numerical places of the machine, those elements of the sets of connections corresponding to lower numerical places which are located in a higher numerical place being combined with each other.

20. In a computing machine, the combination of a number indicating means, means for giving the results of the computations, and connecting means between the number

indicating means and the result giving means, said connecting means including a set of independently movable connection elements corresponding to each of the lower numerical places of the machine, each set of connections extending through its own numerical place and higher numerical places, those connecting elements of the sets corresponding to lower numerical places being combined with each other in the higher numerical places.

21. In a computing machine, the combination of a number indicating means having a plurality of members on which numbers may be indicated, means for giving the results of the computations, and connecting means between the number indicating means and the result giving means, said connecting means including a set of connections for each of the lower numerical places in the machine, each set extending through its own numerical place and higher numerical places and being controlled by the significant figures of one member of the number indicating means in both the lower and higher numerical places, those elements of the sets corresponding to lower numerical places being combined with each of the higher numerical places, the control of the elements forming parts of the sets corresponding to lower numerical places being different than that of the connections forming the sets corresponding to higher numerical places.

22. In a computing machine, the combination of a number indicating means, means for giving the results of the computations, and connecting means between the number indicating means and the result giving means, said connecting means including a set of connections corresponding to each of the lower numerical places of the machine, each set of connections extending through its own numerical place and higher numerical places, the combined elements being controlled by the significant figures of the higher places to present on the result giving means one less unit of the respective higher numerical place than is presented by the set of connections corresponding to the higher place.

23. In a computing machine, the combination of a number indicating means, means for giving the results of the computations, and connecting means between the number indicating means and the result giving means, said connecting means including a set of connections corresponding to an irregular value element of the result giving means, said set of connections including two elements, one element corresponding to and being operative with the significant figures of the numerical place in which the irregular value element is located and the other connection corresponding to and being ren-

dered operative with the significant figures of a lower numerical place.

24. In a computing machine, the combination of a number indicating means, means for giving the results of the computations, and connecting means between the number indicating means and the result giving means, said connecting means including a set of connections corresponding to an irregular value element of the result giving means, said set of connections including two elements, one element corresponding to and being operative with the significant figures of the numerical place in which the irregular value element is located and the other connection corresponding to and being rendered operative with the significant figures of a lower numerical place, the connection corresponding to a lower numerical place being controlled by the significant figures of the higher numerical place to present on the result giving means one less unit than is presented by the element corresponding to the higher numerical place.

25. In a computing machine, the combination of a number indicating means, means of giving the results of the computations, and connecting means between the number indicating means and the result giving means, said connecting means including a set of connections corresponding to a value element of the result giving means which is not a multiple of the units of the numerical place in which it is located, said set of connections including an element corresponding to the numerical place in which the irregular value piece is located and an element for each of the sections of the number indicating means of a lower numerical place which corresponds to the fractional part of said irregular value element.

26. In a computing machine, the combination of a number indicating means, means of giving the results of the computations and connecting means between the number indicating means and the result giving means, said connecting means including a set of connections corresponding to a value element of the result giving means which is not a multiple of the units of the numerical place in which it is located, said set of connections including an element corresponding to the numerical place in which the irregular value piece is located and an element for each of the sections of the number indicating means of a lower numerical place which corresponds to the fractional part of said irregular value element, each of said connection elements being differently controlled by the significant figures of the number indicating means in the numerical place containing the irregular value element.

27. In a computing machine, the combination of a number indicating means, means

for giving the results of the computations, and connecting means between the number indicating means and the result giving means, said connecting means including in a higher numerical place a series of elements corresponding to and rendered operative with the significant figures of said higher place when no significant figure in a lower place is operated and a series of elements corresponding to and rendered operative with the significant figures in a lower numerical place of the machine.

28. In a computing machine, the combination of a number indicating means, means for giving the results of the computations, and connecting means between the number indicating means and the result giving means, said connecting means including in a higher numerical place a series of elements corresponding to and rendered operative with the significant figures of said higher place when no significant figure in a lower place is operated and a series of elements corresponding to and rendered operative with the significant figures in a lower numerical place of the machine, the series of elements in the higher numerical place being controlled differently by the significant figures of the number indicating means in that place than are the elements corresponding to the lower numerical place.

29. In a computing machine, the combination of a number indicating means, means for giving the results of the computations, and connecting means between the number indicating means and the result giving means, said connecting means including in a higher numerical place a series of elements corresponding to and rendered operative with the significant figures of said higher place when no significant figure in a lower place is operated and a series of elements corresponding to and rendered operative with the significant figures in a lower numerical place of the machine, the series of elements corresponding to the lower numerical place being controlled by the significant figures of the number indicating means of the higher numerical place to present on the result giving means one less unit of said higher numerical place than is the series of elements corresponding to the lower numerical place.

30. In a computing machine, the combination of a number indicating means, means for giving the results of the computations, and connecting means between the number indicating means and the result giving means, said connecting means including in a higher numerical place a series of elements corresponding to and rendered operative with the significant figures of the number indicating means in said higher place when no significant figure is indicated

in a lower numerical place and any series of elements corresponding to and rendered operative with the significant figures of the number indicating means in each of the 5 lower numerical places.

31. In a computing machine, the combination of a number indicating means, means for giving the results of the computations, and connecting means between the number 10 indicating means and the result giving means, said connecting means including in a higher numerical place a series of elements corresponding to and rendered operative with the significant figures of a number 15 indicating means in said higher place when no significant figure is indicated in a lower numerical place and any series of elements corresponding to and rendered operative with the significant figures of the number indicating means in each of the lower numerical 20 places, the series of connections corresponding to the lower numerical places being controlled by the significant figures of the number indicating means in the higher numerical 25 place to present on the result giving means in said higher place one less of the units of said higher place than is presented by the series of connections corresponding to said higher place.
32. In a subtracting machine, the combination of minuend indicating means, subtrahend indicating means, means for giving the results of the subtractions, and connecting means between the indicating means and the 35 result-giving means, said connecting means including a set of connections corresponding to each of the lower numerical places of the machine, one of said sets of connections being operative with the significant figures of 40 the subtrahend indicating means in a lower numerical place of the machine to present on the result-giving means in a higher place the value of the higher place, less one of its units.
33. In a subtracting machine, the combination of minuend indicating means, subtrahend indicating means, means for giving the results of the subtractions, and connecting means between the indicating means and the 45 result-giving means, said connecting means including a set of connections corresponding to each of the lower numerical places of the machine, the set of connections corresponding to the lowest numerical place 55 in which a significant figure of the subtrahend indicating means is indicated being operative to present on the result-giving means in a higher numerical place the value of the higher place, less one of its units.
34. In a subtracting machine, the combination of minuend indicating means, subtrahend indicating means, means for giving the results of the subtractions, and connecting means between the indicating means and the 60 result-giving means, said connecting means

including a set of connections for each of the lower numerical places of the machine, each of said sets of connections being rendered operative by the significant figures of the subtrahend indicating means in the corresponding numerical place when no significant figure of a lower numerical place has been indicated. 70

35. In a subtracting machine, the combination of minuend indicating means, subtrahend indicating means, means for giving the results of the subtractions, and connecting means between the indicating means and the result-giving means, said connecting means including a set of connections for each of the lower numerical places of the machine, said connecting means being normally inoperative, the one corresponding to the lowest numerical place in which a number has been indicated by the subtrahend indicating 85 means being rendered operative.

36. In a subtracting machine, the combination of minuend indicating means, subtrahend indicating means, means for giving the results of the subtractions, and connecting means between the indicating means and the result-giving means, said connecting means including a set of connections for each of the lower numerical places of the machine, said connecting means being normally inoperative, the one corresponding to the lowest numerical place in which a number has been indicated by the subtrahend indicating means being rendered operative, parts of 90 said operative set of connections being rendered inoperative by the significant figures indicated on the minuend indicating means.

37. In a subtracting machine, the combination of minuend indicating means, subtrahend indicating means, means for giving the results of the subtractions, and connecting means between the indicating means and the result-giving means, said connecting means including a set of connections for each of the lower numerical places of the 105 machine.

38. In a subtracting machine, the combination of minuend indicating means, subtrahend indicating means, means for giving the results of the subtractions, and connecting 115 means between the indicating means and the result-giving means, said connecting means including in a higher numerical place of the machine a series of connections corresponding to and rendered operative with the significant figures of the minuend indicating means in said higher place, and another series of connections corresponding to and rendered operative with the significant figures of the minuend indicating means in a 120 lower numerical place.

39. In a subtracting machine, the combination of minuend indicating means, subtrahend indicating means, means for giving the results of the subtractions, and connect- 130

- ing means between the indicating means and the result-giving means, said connecting means including a series of connections corresponding to and rendered operative with the significant figures of the minuend indicating means in a higher numerical place when no significant figure of the minuend indicating means is indicated in a lower numerical place, and another series of connections corresponding to and rendered operative with the significant figures of the minuend indicating means in each of the lower numerical places of the machine.
40. In a subtracting machine, the combination of minuend indicating means, subtrahend indicating means, means for giving the results of the subtractions, and connecting means between the indicating means and the result-giving means, said connecting means including a series of connections corresponding to and rendered operative with the significant figures of the minuend indicating means in a higher numerical place when no significant figure of the minuend indicating means is indicated in a lower numerical place, and another series of connections corresponding to and rendered operative with the significant figures of the minuend indicating means in each of the lower numerical places of the machine, the series of connections corresponding to the lower numerical places being controlled by the significant figures of the higher numerical place to present on the result-giving means one less unit of the higher numerical place than is presented by the series of connections corresponding to the higher numerical place.
41. In a machine for computing change, the combination of means for indicating the amounts received, means for indicating the amounts of purchases, means for presenting amounts of change, and connecting means between the indicating means and the change-presenting means, said connecting means including a member corresponding to each of the lower numerical places of the machine, each member being rendered operative by the significant figures of the purchase-amount indicating means in the corresponding place when no significant figure of the said indicating means in a lower place has been indicated.
42. In a machine for computing change, the combination of means for indicating the amounts received, means for indicating the amounts of purchases, means for presenting amounts of change, and connecting means between the indicating means and the change-presenting means, said connecting means including a set of connections for each of the lower numerical places of the machine, each of said sets of connections being rendered operative by the significant figures of the purchase-amount indicating means in the corresponding numerical place between the indicating means and in a lower numerical place has been indicated.
43. In a machine for computing change, the combination of means for indicating the amounts received, means for indicating the amounts of purchases, means for presenting amounts of change, and connecting means between the indicating means and the change-presenting means, said connecting means including a member for each of the lower numerical places of the machine.
44. In a machine for computing change, the combination of means for indicating the amounts received, means for indicating the amounts of purchases, means for presenting amounts of change, and connecting means between the indicating means and the change-presenting means, said connecting means including a member for each of the lower numerical places of the machine, the member corresponding to the lowest numerical place in which a significant figure of the purchase amount indicating means is indicated being operative to present on the change-presenting means the differences between the amounts received and purchase amounts.
45. In a mechanical cashier, the combination of means for indicating amounts received, means for indicating the amounts of purchases, means for delivering amounts of change, and connecting means between the indicating means and the change delivering means, said connecting means including a member corresponding to each of the lower numerical places of the machine, the connecting member corresponding to the lowest numerical place in which a significant figure of the purchase-amount indicating means is indicated being operative to cause the change delivering means to deliver in a higher numerical place the value of the higher place less one of its units.
46. In a mechanical cashier, the combination of means for indicating amounts received, means for indicating the amounts of purchases, means for delivering amounts of change, and connecting means between the indicating means and the change delivering means, said connecting means including a plurality of sets of connections one of which is rendered operative with the significant figures of the purchase amount indicating means in the lowest numerical place of the machine in which such a figure is indicated, another set being rendered operative with an element of the amount-received indicating means corresponding to an irregular money element, and another set being rendered operative with the elements of the amount-received indicating means representing irregular combinations of money elements, said operative sets of connections serving to cause the change delivering means

to deliver the differences between amounts received and purchase amounts.

47. In a mechanical cashier, the combination of means for indicating amounts received, means for indicating the amounts of purchases, means for delivering amounts of change, and connecting means between the indicating means and the change delivering means, said connecting means including a plurality of members, one of which is rendered operative with the significant figures of the purchase-amount indicating means in the lowest numerical place in which such a figure is indicated, another member being rendered operative with an element of the amount-received indicating means representing an irregular value element, and another member being rendered operative with elements of the amount-received indicating means representing an irregular combination of value elements, said members serving to cause the change delivering means to deliver the differences between amounts received and purchase amounts.
48. In a mechanical cashier, the combination of means for indicating amounts received, means for indicating the amounts of purchases, means for delivering amounts of change, and connecting means between the indicating means and the change indicating means, said connecting means including a member corresponding to each of the lower numerical places of the machine, each member being rendered operative by the significant figures of the purchase-amount indicating means in the corresponding numerical place when no significant figure of the said indicating means has been indicated in a lower numerical place.
49. In a mechanical cashier, the combination of means for indicating amounts received, means for indicating the amounts of purchases, means for delivering amounts of change, and connecting means between the indicating means and the change delivering means, said connecting means including a set of connections for each of the lower numerical places of the machine, each of said sets of connections being rendered operative by the significant figures of the purchase-amount indicating means in the corresponding numerical place when no significant figure of the said means has been indicated in a lower numerical place.
50. In a mechanical cashier, the combination of means for indicating amounts received, means for indicating the amounts of purchases, means for delivering amounts of change, and connecting means between the indicating means and the change delivering means, said connecting means including a set of connections for each of the lower numerical places of the machine, each of said sets of connections being rendered operative by the significant figures of the purchase-

amount indicating means in the corresponding numerical place when no significant figure of the said means has been indicated in a lower numerical place, the operative set of connections being rendered inoperative to cause the change delivering means to deliver any money element of greater value than the lowest value indicated on the amount received indicating means.

51. In a mechanical cashier, the combination of means for indicating amounts received, means for indicating the amounts of purchases, means for delivering amounts of change, and connecting means between the indicating means and the change delivering means, said connecting means including a member for each of the lower numerical places of the machine.

52. In a mechanical cashier, the combination of means for indicating amounts received, means for indicating the amounts of purchases, means for delivering amounts of change, and connecting means between the indicating means and the change delivering means, said connecting means including a member for each of the lower numerical places of the machine, said members being normally rendered inoperative, and only that member being rendered operative which corresponds to the lowest numerical place in which a significant figure of the purchase-amount indicating means has been indicated.

53. In a subtracting machine means for indicating the minuend, means for indicating the subtrahend, each of said indicating means including sufficient elements in a numerical place of the machine to indicate the value of such numerical place less one of its units, means for presenting the differences between numbers indicated on the indicating means, and connecting means between the indicating means and the difference presenting means, said connecting means including a member for each of the lower numerical places of the machine.

54. In a subtracting machine, means for indicating the minuend, means for indicating the subtrahend, each of said indicating means including sufficient elements in a numerical place of the machine to indicate the value of such numerical place less one of its units, means for presenting the differences between numbers indicated on the indicating means, and connecting means between the indicating means and the difference presenting means, said connecting means including a member for each of the lower numerical places of the machine, all said members being rendered inoperative excepting that corresponding to the numerical place in which a significant figure is indicated on the purchase-amount indicating means.

55. In a machine for facilitating money transactions, the combination of means for indicating amounts of money received,

means for indicating amounts of purchases or of money paid out, means for presenting money amounts in values corresponding to the elements of a monetary system, and connecting means between the amount indicating means and the amount presenting means, said connecting means being constructed to render the amount presenting means operative to present amounts representing the difference between the amounts received and the amounts paid out or representing the amounts paid out alone, and connecting means between the paid-out indicating means and the amount presenting means controlled only by the paid out indicating means, said connecting means being constructed to render the amount presenting means operative to present amounts indicated on such paid out amount indicating means, and means for rendering one or the other of said connecting means inoperative.

56. In a machine for facilitating money transactions, the combination of means for indicating amounts received, means for indicating amounts of purchases, means for presenting amounts of change, and connecting means between the indicating means and the change presenting means, said connecting means including a plurality of members, certain of said members being operative to present on the change presenting means differences between amounts received and amounts of purchases, and certain other of said members being operative to present on the change presenting means amounts of money indicated on one of said amount indicating means.

57. In a machine for facilitating money transactions, the combination of means for indicating amounts received, means for indicating amounts of purchases, means for presenting amounts of change, and connecting means between the indicating means and the change presenting means, said connecting means including a plurality of members for each numerical place of the machine, one of said members being rendered operative with the significant figures of the purchase-amount indicating means in the corresponding place to present on the change presenting means the differences between amounts of money received and amounts of purchases and another of said members being rendered operative to present on the change presenting means amounts of money indicated on one member of the indicating means.

58. In a machine for facilitating money transactions, the combination of means for indicating amounts received, means for indicating amounts of purchases, means for presenting amounts of change, and connecting means between the indicating means and the change presenting means, said connecting means including a plurality of members certain of which are rendered operative with

the significant figures of the purchase-amount indicating means to present on the change-amount presenting means the differences between amounts of money received and amounts of purchases, and certain other of said connections being rendered operative with the significant figures of the purchase-amount indicating means to present on the change-amount presenting means amounts of money indicated on the purchase-amount indicating means.

59. In a machine for facilitating money transactions, the combination of means for indicating amounts received, means for indicating amounts of purchases, means for presenting amounts of change, and connecting means between the indicating means and the change presenting means, said connecting means including a plurality of members corresponding to each numerical place of the machine, one of the members corresponding to each place being rendered operative with the significant figures of the purchase-amount indicating means in the corresponding place when no such figure is indicated in a lower place to present on the change-amount presenting means the differences between amounts received and amounts of purchases, and another member corresponding to each place being rendered operative with the significant figures of the purchase-amount indicating means to present on the change amount indicating means amounts of money indicated on the purchase-amount indicating means.

60. In a machine for facilitating money transactions, the combination of means for indicating amounts received, means for indicating amounts of purchases, means for presenting amounts of change, and connecting means between the indicating means and the change-amount presenting means, said connecting means including a plurality of sets of connections, certain of said sets of connections being operative to present on the change-amount presenting means differences between amounts received and amounts of purchases, and certain other of said sets of connections being operative to present on the change-amount presenting means amounts of money indicated on one of said amount indicating means.

61. In a machine for facilitating money transactions, the combination of means for indicating amounts received, means for indicating amounts of purchases, means for presenting amounts of change, and connecting means between the indicating means and the change-amount presenting means, said connecting means including a plurality of sets of connections for each numerical place of the machine, one of said sets of connections in each place being rendered operative with the significant figures of the purchase-amount indicating means in the correspond-

- ing place to present on the change-amount presenting means the differences between amounts received and amounts of purchases, and another of said sets of connections being rendered operative to present on the change-amount presenting means amounts indicated on one member of the indicating means. 5
62. In a machine for facilitating money transactions, the combination of means for indicating amounts received, means for indicating amounts of purchases, means for presenting amounts of change, and connecting means between the indicating means and the change-amount presenting means, said 10 connecting means including a plurality of sets of connections certain of which are rendered operative with the significant figures of the purchase-amount indicating means to present on the change-amount presenting means the differences between amounts received and amounts of purchases, and certain other of said sets of connections being rendered operative with the significant figures of the purchase-amount indicating 15 means to present on the change-amount presenting means amounts indicated on the purchase-amount indicating means. 20
63. In a machine for facilitating money transactions, the combination of means for indicating amounts received, means for indicating amounts of purchases, means for presenting amounts of change, and connecting means between the indicating means and the change-amount presenting means, said 25 connecting means including a plurality of sets of connections corresponding to each numerical place of the machine, one of the sets of connections corresponding to each place being rendered operative with the significant figures of the purchase-amount indicating means in the corresponding place when no such figure is indicated in a lower place, to present on the change-amount presenting means the differences between 30 amounts received and amounts of purchases, and another set of connections corresponding to each place being rendered operative with the significant figures of the purchase-amount indicating means to present on the change-amount presenting means amounts of money indicated on the purchase-amount indicating means. 35
64. In a computing machine, the combination of number indicating means having a plurality of members on which numbers may be indicated, means for giving the results of the computations, means whereby said result giving means are caused to present the results of the computations, and means whereby said result giving means are caused to present a number indicated on one member of the number indicating means. 40
65. In a computing machine, the combination of number indicating means having a plurality of members on which numbers may 45

be indicated, means for giving the results of the computations, means whereby said result giving means are caused to present the results of the computations, and means whereby said result giving means may be caused to present the numbers indicated on a plurality of members of the number indicating means. 70

66. In a subtracting machine, the combination of minuend indicating means, subtrahend indicating means, means for presenting the results of the subtractions, and means whereby numbers presented on one member of the indicating means may be indicated on the result giving means. 75

67. In a subtracting machine, the combination of minuend indicating means, subtrahend indicating means, means for presenting the results of the subtractions, and means whereby the numbers indicated on each member of the indicating means may be indicated on the result giving means. 80

68. In a subtracting machine, the combination of minuend indicating means, subtrahend indicating means, means for presenting the results of the subtractions, means whereby numbers indicated on the subtrahend indicating means may be presented on the result giving means and means for rendering inoperative either the subtraction result presenting means or the subtrahend result giving means. 85

69. In a subtracting machine, the combination of minuend indicating means, subtrahend indicating means, means for presenting the results of the subtractions, and connecting means between the indicating means and the result giving means whereby the result giving means is caused to present the results of subtractions, and connections independent of said connecting means between one member of the indicating means and the result giving means. 90

70. In a subtracting machine, the combination of minuend indicating means, subtrahend indicating means, means for presenting the results of the subtractions, and connecting means between the indicating means and the result giving means whereby the result giving means is caused to present the results of subtractions, and connections independent of said connecting means between the subtrahend indicating means and the result giving means. 105

71. In a subtracting machine, the combination of a minuend indicating means, subtrahend indicating means, means for presenting the results of the subtractions, and connecting means between the indicating means and the result giving means whereby the result giving means is caused to present the results of subtractions, and connections independent of said connecting means between each member of the indicating means and the result giving means. 110

72. In a machine for computing change, the combination of means for indicating amounts received, means for indicating amounts of purchases, means for presenting amounts of change, and connecting means between the indicating means and the change-amount presenting means whereby said change-amount presenting means may be caused to present amounts indicated on each member of the indicating means as well as amounts of change.

73. In a machine for computing change, the combination of means for indicating amounts received, means for indicating amounts of purchases, means for presenting amounts of change, and connecting means between the indicating means and the change-amount presenting means whereby said change-amount presenting means is caused to present amounts of change, and connections independent of said connecting means whereby said change-amount presenting means may be caused to present amounts indicated on each member of the indicating means.

74. In a machine for computing and recording money transactions, the combination of means for indicating amounts received, means for indicating amounts of purchases, means for presenting amounts of change, means for recording amounts of purchases, connecting means between the indicating means and the change-amount presenting means, connections independent of said connecting means between the amount-received indicating means and the change-amount presenting means whereby amounts received are presented by the change-amount presenting means, and connections independent of said connecting means between the purchase-amount indicating means and the recording means.

75. In a mechanical cashier, the combination of number indicating means, receptacles for money of different denominations and connecting means for controlling the delivery of money from said receptacles, said connecting means including a series of independently movable members, means whereby certain of said members may be locked, and means for actuating such of the members as are not locked.

76. In a mechanical cashier, the combination of number indicating means, receptacles for money of different denominations, connecting means for controlling the delivery of money from said receptacles, said connecting means including a series of spring-impelled members, means for normally retaining said members in a retracted position, said number-indicating means serving to lock certain of said tumblers in their retracted position.

77. In a mechanical cashier, the combination of a plurality of receptacles for

money, a series of normally inoperative connections for controlling the delivery of money from said receptacles, key operated means for locking certain of said devices in their inoperative positions, and means whereby the devices which are not locked are rendered operative for discharging money.

78. In a mechanical cashier, the combination of a plurality of receptacles for money of different denominations, a series of normally inoperative connections for controlling the delivery of money from said receptacles, key-operated means for locking certain of said connections in their inoperative positions, and means whereby the devices which are not locked are rendered operative for discharging money.

79. In a mechanical cashier, the combination of a plurality of receptacles for money, a series of normally inoperative connections for controlling the delivery of money from said receptacles, key operated means for locking certain of said connections in their inoperative positions, and means whereby the keys may be operated in any desired order.

80. In a mechanical cashier, the combination of a plurality of receptacles for money, two sets of keys for controlling the delivery of money from said receptacles and connections between said sets of keys and receptacles, said connections including a series of normally inoperative members, devices operated by said sets of keys for certain of the members, and means whereby the members which are not locked are rendered operative for discharging money.

81. In a mechanical cashier, the combination of a series of receptacles for money of different denominations, a series of devices for controlling the delivery of money from said receptacles, two sets of keys for rendering certain of said devices inoperative, and means independent of said sets of keys for actuating the operative devices to control the delivery of money.

82. In a machine of the class described, the combination of purchase keys, deposit keys, money receptacles, connecting bars with means giving them a bias normally toward their operative positions but normally held in their inoperative positions, a lock for holding said bars in their inoperative positions, a set of locks under the control of the purchase and deposit keys for locking said bars, the particular locks operative at any time being dependent upon the particular keys operated, selecting devices, one for each connecting bar, adapted to be moved by its bar into operative position when the latter moves into its operative position, means for moving the money receptacles controlled by the selecting devices and operating means, adapted to release the

first lock on the connecting bars through the selecting devices that have been operated to move the corresponding money receptacles, to eject the proper change.

5 83. In a machine of the class described, the combination of purchase keys, deposit keys, connecting bars under the control of both of said sets of keys, and two sets of locks for said connecting bars, one set locking all of the bars and adapted to be removed from operative position by the operating means and the other set of locks adapted to be operated jointly by the purchase keys and deposit keys operated, and 10 operating means.

84. In a machine of the class described, the combination of purchase keys, deposit keys, connecting bars, means tending to force said connecting bars toward their operative position, devices normally holding said connecting bars against movement, springs for moving them into operative positions, means for releasing said bars from their inoperative positions, locks under the 20 control of the purchase keys and deposit keys for further locking certain bars dependent upon the keys operated, and means for returning to their original positions the bars that have been operated.

30 85. In a machine of the class described, the combination of a series of money receptacles, a series of selectors, one for each receptacle, each selector composed of a movable part normally in inoperative position but adapted to be engaged and moved into operative position, a lock for each selector for holding it in operative position and operating means for moving through the movable parts of the selectors that have been set 35 in position their corresponding money receptacles, and ejectors adapted to be actuated by the operating means for ejecting change from such receptacles.

86. In a machine of the class described, 45 the combination with a plurality of money receptacles, of tumbler bars controlling said receptacles, springs normally tending to move said tumblers to receptacle controlling positions, a series of keys, and key operating plates for preventing movement of said tumblers.

55 87. In a machine of the class described, the combination with a plurality of rotary money receptacles, of devices for rotating said receptacles to money discharging positions, a plurality of tumblers controlling said rotating means, springs tending to move said tumblers to operative position, a series of keys, and plates adapted to be 60 moved by said keys to positions preventing operation of said tumblers.

88. In a machine of the class described, the combination of a plurality of money receptacles and spring operated tumblers for

controlling the discharge of money from 65 said receptacles, of a set of deposit keys, and connections whereby each deposit key prevents movement of tumblers controlling the corresponding money receptacle and all receptacles of higher value. 70

89. In a machine of the class described, the combination with a plurality of money receptacles and spring operated tumblers controlling the discharge of money from 75 said receptacles, of a series of deposit keys, a series of latching plates, one for the tumblers appropriate to each money receptacle, and having lugs overlapping the latches of next higher values, and connections whereby each deposit key moves the corresponding 80 latch to position latching its tumblers.

90. In a machine of the class described, the combination with a series of tumblers, means for holding said tumblers in normally inoperative position, a plurality of cash receptacles, means for discharging money from 85 said receptacles, devices whereby said tumblers control said discharging means, a plurality of keys having connections to permit said tumblers to be operated when the keys 90 are depressed, connections tending to move said tumblers to operative position, a main operating mechanism for moving said cash receptacles to discharging position, and connections from said tumblers to control said 95 receptacle movement.

91. In a machine of the class described, the combination with a series of tumblers, means for holding said tumblers in normally inoperative position, a plurality of cash receptacles, means for discharging money from 100 said receptacles, devices whereby said tumblers control said discharging means, a plurality of keys having connections to permit said tumblers to be operated when the 105 keys are depressed, springs tending to move said tumblers to operative position, a main operating mechanism for moving said cash receptacles to discharging position, and connections from said tumblers to control said 110 receptacle movement.

92. In a machine of the class described, the combination with a plurality of money holding receptacles, and means for ejecting money therefrom, of two sets of devices each 115 set constructed to control said ejecting means, a set of keys common to the said sets of devices and constructed to determine movement thereof and a hand operated element having connections to render said sets 120 of devices alternately operative or inoperative.

93. In a machine of the class described, the combination with a plurality of money receptacles and two series of tumblers controlling the discharge of money from 125 said receptacles, of a bank of purchase keys determining the movement of said tumblers,

and a hand-operated element serving to lock one or the other of said sets of tumblers depending upon its position.

94. In a machine of the class described, the combination with a plurality of money receptacles and a bank of purchase keys, of a set of tumblers controlling the discharge of change from said receptacles, a set of tumblers controlling the discharge of money paid out from said receptacles, devices whereby said bank of keys determines the movements of both sets of tumblers, devices for locking either of said sets of tumblers at will, and a hand-operated device for operating said tumbler locking device.

95. In a machine of the class described, the combination with a plurality of money receptacles, of a series of deposit keys operating said receptacles, a series of purchase keys, two sets of tumblers controlled by said purchase keys and serving to determine the amount of money ejected from said receptacles, and a "paid out" manipulative device having connections to lock one of said sets of tumblers and also to lock said deposit keys.

96. In a machine of the class described, the combination with a plurality of money receptacles and a bank of purchase keys, of two sets of tumblers controlled by said purchase keys and serving to determine the amount of money ejected from said receptacles, a "paid out" manipulative device and connections from said device for locking one of said sets of tumblers and for unlocking the other set.

97. In a machine of the class described, the combination with a plurality of rotary money receptacles, of a series of keys, and a set of tumblers controlling the rotation of said money receptacles, with devices whereby each key permits tumblers indicative of its own value to be moved to operative position.

In testimony whereof, I have signed my name to this specification, in the presence of two subscribing witnesses.

ISAAC S. DEMENT.
